[57] ABSTRACT

Apparatus is provided for displaying configurations on a surface, such as the face of a cathode-ray tube, with an energy beam, such as a cathode-ray tube electron beam. The beam is deflected with reference to first and second perpendicularly related axes in response to positioning signals for positioning the beam on the surface at selected positions in accordance with position command signals. A control circuit provides configuration signals for sequentially positioning the beam relative to the two axes to provide a plurality of incrementally spaced images which, in turn, define a configuration. The magnitude of the configuration signals is dependent on the selected position, and a configuration size control circuit serves, in response to size command signals, to change the magnitude of the configuration signals and thereby change the size of the configuration.

CONTROL OF CONFIGURATION SIZE AND INTENSITY

This is a division of our copending application, Ser. No. 591,734, filed on Nov. 3, 1966, now U.S. Pat. No. 3,588,870, and assigned to the same assignee.

This invention relates to the art of displaying configurations and, more particularly, to displaying configurations on a surface with an energy beam.

The invention is particularly applicable in conjunction with cathode ray tubes wherein configurations are displayed by an electron beam on the face of the tube; although the invention is not limited thereto and may be used, for example, with laser beams.

One application of the present invention is the utilization of a configuration display device, such as a cathode-ray tube, in conjunction with photocomposition, including phototypesetting, apparatus. In such a system it is desirable to display graphical images or characters on the face of the tube by means of a plurality of incrementally spaced visual images on the tube face. Consequently, the size of the graphical image or character is dependent on the spacing between adjacent visual images that, in turn, define the configuration. To achieve flexibility in such a system it is desirable to provide circuitry for, in response to command signals, controlling the spacing between the incrementally spaced images.

Depending on the type of apparatus used for generating the energy beam, nonlinear beam deflection response characteristics may be present; to wit, the incremental spacing between adjacent images may vary with positions on the display surface. Consequently, to achieve uniform spacing between adjacent images regardless of their position on the display surface, it is desirable to provide circuitry for varying the deflection control signals, which determine the configuration size as configurations are generated at various locations. It is also desirable to change the intensity of the energy beam in accordance with configuration location.

The present invention is directed toward apparatus for satisfying the foregoing needs and, briefly, includes means for deflecting an energy beam with reference to first and second perpendicularly related axes; first control circuitry for applying positioning signals to the deflecting means so as to position the beam at selected positions on the display surface in accordance with first command signals; second control circuitry for applying configuration signals to the deflecting means to sequentially position the beam relative to the axes so as to provide a plurality of incremental spaced images which define the configuration, the magnitude of these configuration signals being dependent on the selected configuration position; and, configuration control circuitry for, in response to configuration size command signals, changing the magnitude of the configuration signals so as to thereby change the size of the configurations.

In accordance with a more limited aspect of the invention, the configuration size control circuitry includes storage means for storing digital representations of the various configuration sizes so that in response to a size command signal, the storage means provides digital signals representative of a particular configuration size. These digital signals are decoded for purposes of modifying the magnitude of the configuration signals.

In accordance with a still further aspect of the present invention, beam control means serves to vary the intensity of the beam in dependence upon the configuration size in effect.

The primary object of the present invention is to provide apparatus for controlling the size of a configuration formed on the display surface by an energy beam.

Another object of the present invention is to provide configuration size control circuitry wherein various configuration sizes are stored in the form of digital representations permitting rapid readout of the stored information.

It is a still further object of the present invention to provide configuration size control circuitry wherein the configuration size is maintained uniform throughout various display positions on a display surface.

In accordance with a still further object of the present invention, configuration display control circuitry is provided

wherein the intensity of energy beam images on a display surface is varied in accordance with the configuration size in effect.

The foregoing and other objects and advantages of the invention will become more readily apparent from the following description taken in conjunction with the accompanying drawings in which:

FIG. 1 is a flow chart showing the digitation of the letter A, the conversion of the digitized letter to a paper tape and the recording of the letter onto a character disc;

FIG. 2 is a view of the digitized letter A;

FIG. 3 is a detail drawing of the digitized letter A showing the scanning pattern;

FIG. 4 is a detail view of a portion of the paper tape produced by the apparatus when scanning a digitized letter;

FIG. 5 is a detail view of a portion of the character disc showing a track containing the digitized letter recorded thereon along with control information;

FIG. 6 is a block diagram of the encoder generator control for placing on the character disc the digitized letter;

FIG. 7 is a detail schematic diagram of the encoder generator correction control circuit;

FIG. 8 is a pictorial representation of the phototypesetting system of this invention illustrating the equipment used in the production of characters from a magnetic tape;

FIG. 9 is a representation of the information contained on the control tape used to direct the operation of the phototypesetter of this invention;

FIG. 10 is a block diagram showing the distribution of information which was contained on the magnetic tape controlling the phototypesetting unit;

Figs. 11A and 11B together comprise a block diagram of the buffer memory circuit;

Figs. 12A and 12B together comprise a detailed schematic diagram of the decoder circuit;

FIG. 13 is a detailed schematic diagram of the eight input NOR decoder circuits;

FIG. 14 is a block diagram showing the character generator raster and Z-axis control circuit associated with the character generator;

FIG. 15 is a schematic diagram of the pulse forming circuit for generating synchronizing pulses;

FIG. 16 is a schematic diagram of the character generator pulse forming and selection circuit;

FIG. 17 is a schematic diagram of the character generator raster and Z-axis control;

FIG. 18 is a graph showing the relationship with respect to time among (A) the up-down signal, (B) the vertical deflection voltage, (C) the horizontal deflection voltage, and (D) the horizontal step pulse;

FIG. 19 shows the effect on character size by varying the size voltage to the horizontal and vertical D/A control circuits;

FIG. 20 is a block diagram of the horizontal control circuit of this invention;

Figs. 21A through 21D together comprise a detailed schematic diagram of the horizontal control system;

FIG. 21E shows the relationship of the circuits contained in FIGS. 21A through 21D;

FIG. 22 is a schematic diagram of one of the major horizontal deflection digital to analogue (D/A) circuits;

FIG. 23 is a schematic diagram of a constant current voltage ladder used for the interpolation D/A, character D/A and leading D/A control circuits;

FIG. 24 is a schematic diagram of the reed relay point size circuit;

FIG. 25 is a schematic diagram of the intensity control for the cathode-ray tube;

FIG. 26 is a schematic diagram of the leading control circuit; and,

FIG. 27 is a detailed schematic diagram of the control clock in the leading circuit.

CHARACTER ENCODING

Referring now to the drawings, which show a preferred embodiment of this invention, and particularly FIGS. 1 through 5, a method and apparatus employed for converting a basic letter or symbol into a coded signal are shown. This signal may be placed in a digital memory device such as a photographic character generator disc, drum or tape for later use in the production of characters on the face of a cathode ray tube. The character generator member thus created will thereafter form a significant portion of the character generation system to be later described.

The basic character or symbol 10, as shown at A in FIG. 1 is first digitized, or converted into a form usable in the character generator member, by placing the letter on an analyzing grid 11, shown at B in FIG. 1. The letter may then be digitized either manually or by a computer so that the digitized form of the letter 12 (shown at C in FIGS. 1 and 2) conforms to the blocks of a graph. The letter is thus converted from an analogue form into a digital form having an appearance closely resembling that of the original letter.

The digitized character 12 is then placed on the scanner mechanism 15 shown at D in FIG. 1 which comprises a transparent drum 16 having a light positioned internally and provided with a photocell 17 adapted to scan the digitized character. The drum 16 may be rotated by a stepping motor 18 in incremental steps such that the digitized letter is moved an amount equal to one space on the graph for each electrical pulse applied to the motor 18. The photocell 17 is slidably mounted on a guide bar 19 and is driven by a cord 20 reeved on an idler pulley 21 at one end and a driving reel 22 at the other end. The driving reel is connected to a second stepping motor 23 which causes the photocell to move in incremental steps, each step corresponding to one block of the graph forming the digitized character. The photocell is positioned in the center of each graph block after each incremental step.

The output of the photocell is directed through an amplifier which controls a paper tape punching mechanism. Thus a reel of paper tape 26 is provided at the side of the scanner mechanism 15 and supplies the tape 27 through the punching mechanism 28. For each incremental movement of the photocell to the left (in the upper direction with respect to the character being analyzed), the paper tape will be punched with a hole in a channel which will hereafter be designated as the "up channel." Likewise, for each incremental movement of the photocell to the right, corresponding to the downward scanning motion with respect to the character, a hole will be punched in the paper tape in another channel hereafter designated as the "down channel." Each time the photocell scans an opaque area representing a part of the character being digitized, a hole will be punched in the paper tape in that channel reserved for that specific character. Thus, a paper tape, a detail of which is shown in FIG. 4, will contain an up channel 30, a down channel 31, and a channel 32 reserved for the character being digitized.

In this description, only one character is shown being recorded in digital form on the paper tape. It is to be understood, however, that more than one character may be recorded on the same tape so long as the up channel and the down channel for each character are of identical length, and synchronized. In that way, only one set of up-down information will be required for the several characters which may be recorded on a single tape.

Referring now to FIGS. 2 and 3, where the scanning sequence for the letter A is shown, the photocell first moves upwardly in a series of steps controlled by motor 23 until it has scanned all of the available blocks in the first vertical row on the left. Once the first row has been completely scanned, the motor 18, controlling the horizontal movement of the digitized character 12, is then pulsed one step to cause the letter to rotate to the right with respect to the photocell and the photocell is caused thereafter to scan downwardly on the

next row. Each time the photocell reads an area which has been blackened, such as at 36 in FIG. 2, a hole will be punched in that channel reserved for the character on the paper tape. Thus, the characters will be scanned in a raster-type pattern. An "end of character" (EOC) signal is provided at the lower right hand portion of the block in the last vertical row which contains character information. In this form of the invention, the end of character block 37 (FIG. 3) may be either on a row which is scanned upwardly or downwardly, depending on the width information which is to be assigned to the particular character being recorded. While this end of character signal will not be printed or displayed by the cathode ray tube, it will be used to activate certain control circuits in the phototypesetting system as will be described in detail later.

Once a digitized character has been completely scanned and a paper tape produced therefrom, the tape 27 will be placed on a reading machine 40, as shown at E in FIG. 1. The tape is scanned and the information contained therein ultimately placed on a character generator disc 41. This character generator disc 41 consists of a photographic plate mounted on a spindle 42 and driven by a motor 43 (FIG. 6). A set of bands on the disc 41 contain both control information and character information for use in the phototypesetting machine. In one embodiment of this invention twelve bands are included on each character generator disc 41, and each band contains a total of 35 tracks of information. A portion of one band of information is shown in FIG. 5. One track of information, for example 41a is used to represent the up-down information, another track 41b is used as a fiducial channel to indicate the beginning of the character information, while another track 41c is used to record the synchronizing pulses obtained from a master character disc, and 32 tracks 41d in each band are used to record the character information stored on the paper tape. It can be seen therefore that, as a practical matter, more than one character would be recorded on a disc at the same time, and it is for this reason that several characters are recorded on a single paper tape at one time.

40 The particular manner in which the information stored on the paper tape is transferred onto the character disc is shown in FIGS. 6 and 7. A master disc 45 is mounted on a common shaft or spindle 42 with the undeveloped photographic plate 41 which is to become the character generator disc. The master disc 45 has two channels of equally spaced marks, channel 46 containing 215 equally spaced marks which will be used as the synchronization pulses, and a set of marks 47 which divide the character disc into four equal quadrants. A source of light 50 is provided on one side of the transparent master disc 45 while four photomultiplier tubes 51 are spaced at intervals around the master disc and focused on the channel 46 containing the synchronization marks. The photomultiplier tubes 51 are all connected to a common buss 52 and function to average the signals received from the disc so that a single synchronization pulse is applied to a voltage-sensitive pulse-forming circuit such as a Schmitt trigger 53. A fifth photomultiplier tube 54 is focused on the channel 47 containing the quadrant marks and the output of this photomultiplier tube is applied to the pulse forming circuit or Schmitt trigger 55.

60 The synchronizing marks contained on channel 46 on the master disc will be placed directly onto the undeveloped character generator disc 41 by applying the output of Schmitt trigger 53 directly through line 57 to one of the glow modulator tubes 60. In the apparatus shown in FIG. 6, only nine glow modulator tubes are shown, but it is to be understood that a greater or lesser number of glow modulator tubes may be provided. One glow modulator tube will cause a single track to be applied to the undeveloped photographic emulsion on the 65 character generator disc 41, and the creation of the character generator disc, which may be necessary to cause several of the operations described below to occur before a complete disc is created. The light output from each of the glow modulator tubes 60 may be focused by means of lenses 61 onto a fiber optic light transmitting means 62. The output of Schmitt

trigger 53 will also be applied to one of the inputs of AND-gate 65.

The information recorded on the paper tape 27 is sensed by a tape reader 66 contained within the reading machine 40. The information stored on the tape may then be transferred to the character generator disc 41 in the following manner. Push button 67 is momentarily closed and will cause the multivibrator or flip-flop 68 to set and thus apply an enabling output through line 69 to AND-gate 70. It will be noticed that the output from Schmitt trigger 55 is applied along line 71 to gate 70 so that, on the occurrence of a quadrant pulse from the Schmitt trigger 55, the AND-gate 70 will supply a triggering voltage through inverter 72 to set the flip-flop 73 in the quadrant counter and apply an enabling signal on line 74 to the AND-gate 65. The multivibrator or flip-flop 75 is also set at this time to hold the enabling voltage on line 74 to the AND-gate 65. With AND-gate 65 provided with an enabling signal on line 74, each synchronizing pulse sensed by the photomultiplier tubes 51 will cause a pulse to be applied through line 57 to the AND-gate 65 to trigger the single shot pulse circuit 76.

A set of registers or storage multivibrators 80 are connected directly to the output of the tape reader 66 through inverters 81 by way of cable 82. The information stored on the tape will then be applied to the input of the registers 80 and will be recorded thereon at the time a toggle pulse is received from the single shot 76. At this time, the selected glow modulator tube 60 will cause light to be focused onto the character generator disc at the selected locations.

A pulse from AND-gate 65 will also be applied through line 83 into the correction control circuit 84 each time a synchronizing pulse is detected by the photomultiplier tubes 51. As shown in detail in FIG. 7, the correction control system consists of a pair of step command counting flip-flops 85 and 86 and a sprocket counting pair of flip-flops 87 and 88. The sprocket counting flip-flop has its input connected by line 90 to a feed detecting means in the tape reader 66 and has a pulse applied to it on line 90 each time a sprocket or feed hole in the paper tape 27 passes under the detector. The input 83 from the AND-gate 65 is applied to toggle flip-flop 85. The output of this flip-flop is tied to flip-flop 86 as well as to one of the inputs to the output gates 89. In like manner, the outputs of each of flip-flops 87 and 88 are also connected to the output gates 89 in the manner shown.

It is the function of the correction control circuit 84 to control the operation of the tape advancing mechanism to insure that the tape advances at the same rate as synchronizing pulses occur on the master disc 45. Therefore, an output will be applied from the correction control circuit on line 91 to cause the tape reader control 92 to advance the tape one position at the time a synchronizing pulse is obtained on input line 83. Once the tape has advanced, and a signal applied on line 90 into the input of flip-flop 87, the tape advance signal is removed from line 91 and the tape will stop. Therefore, as long as the sprocket counter flip-flops and the step command counter flip-flops are synchronized, the tape will remain in synchronization with the master control disc.

The correction control circuit 84 also provides that if the paper tape 27 is behind, the sprocket counter circuits 87 and 88 will permit an output to be applied to the tape reader control 92 until synchronization is again obtained. On the other hand, if the paper tape has advanced one step too far, no output will be permitted on line 91 to the tape reader control until the sprocket command counter has sensed the required number of pulses coming in on line 83. In other words, the correction control circuit corrects for errors of plus or minus one step.

Also connected to the cable 82, which carries the information recorded on the tape, are control circuits 95, 96 and 97 which detect the occurrence of certain tape control functions. For example, detector 95 detects the occurrence of a feed signal on the tape which causes the tape reader control to advance until the feed code or codes have been eliminated. In

like manner, the delete code detector 96 will also cause the tape reader control to advance the tape without the recordation of that information onto the character generator disc 41. A stop code detect 97 is also provided to terminate the operation of all of the circuits shown in FIG. 6. Thus, when a stop code is detected, a reset signal will be applied on line 98 to reset the flip-flops in the correction control circuit 84, the reader registers 80, and the flip-flop 75.

Once the master disc 45 has completed one revolution, the quadrant counter, consisting of flip-flops 73 and 99, will cause a reset pulse to be applied to the flip-flop 68, thereby removing the enable signal on line 69 to the AND-gate 70 and thereafter prevent further pulses from being applied through AND-gate 65 to the correction control system. Therefore, no further toggle pulses will be applied to the reader register and the tape 27 will cease to pass through the reader register. This is necessary, in order to prevent double exposure of the character generator disc 41.

While it has been shown in this embodiment that the information on the tape will be applied to the unexposed character disc four times before the circuit is disabled, it is contemplated that in other embodiments of this invention, the number of times that a particular band of information may be applied to the disc will depend upon the amount of information required to be contained in that band. Therefore, some bands may be divided twenty times, for example.

After the disc 41 has been exposed and the desired number of bands have been placed thereon, which may require that the disc be exposed several times although at different locations, the photosensitive surface will be developed in the conventional manner to make a permanent record of the marks which have been applied thereto and will thereafter be utilized as the master character generator disc in the phototypesetting system.

GENERAL DESCRIPTION OF THE CATHODE-RAY TYPESETTING SYSTEM

Referring now to FIG. 8, which is a pictorial representation of the complete cathode-ray typesetting system of this invention, a control record such as a magnetic tape 110 is shown mounted in a tape transport and reader mechanism 111. The purpose of this tape is to control the entire operation of the system, and it contains not only character selection information but also function information such as leading, indent, character point size, and interword space information. It is understood that the input to the typesetting system could also be directly connected to the output of a computer. The output of the tape reader is applied to a buffer memory storage circuit 112 thus permitting the tape to run at an optimum rate through the tape reader, while at the same time releasing the information for use at the required utilization rate of the remainder of the system. As will be explained in connection with the block diagram shown in FIGS. 11A and 11B, the buffer memory controls the operation of the tape transport.

The output of the buffer storage 112 is then passed to decoding circuits 113 where the information is routed to the various components which comprise the remainder of the cathode ray phototypesetting system. One of the outputs from the decoder 113, for example, is sent to the character generator 114 and selects the character therein which will be displayed on the face of the cathode-ray tube 115. An output of the character generator 114 is also applied to a horizontal control circuit 116 where the width information of the character being printed is to be stored. The horizontal control circuit 116 is used to control the horizontal control circuit 116 is used to control the horizontal position of the character on the face of the cathode-ray tube 115.

The decoder output is also sent to the horizontal control circuit so that interword spaces, indent commands, and other similar signals controlling the position of the line of type may be used. The point size of the character, for example, is also stored in the horizontal control circuit in response to the infor-

mation recorded on the magnetic tape 110 and causes the horizontal control circuit 116 to alter the size of the character in response to that information. The output of the decoder circuit may also be applied to a camera and leading control circuit 117 which in turn supplies an output to the leading motor 18. A photographic material such as film or paper 119 is provided and the characters displayed on the face of the cathode-ray tube are focused thereon by means of the lens 120.

Each character is therefore written individually on the face of the cathode-ray tube and is located at precisely the position it should occupy in a line of type. At the end of each line, the film 119 will be advanced by an amount determined by leading information from the magnetic tape, and a new line of type started.

As previously explained, both the character code information and function information is recorded on the magnetic tape 110. For purposes of explanation, a portion of this magnetic tape is shown in FIG. 9 and has the information recorded thereon in what is termed a double octal code with the small squares representing a binary one. The double octal code means that a pair of three bit codes are used to represent the stored information. In the example shown, the first code at the left of the tape is a double octal code 16 and is represented in the double octal system by binary number 001110. The first three digits, 001, are the binary representation for the numeral 10, while the binary digit 110 represents the number 6. In this example, the least significant digit is placed on the right of each code.

In the example shown in FIG. 9, the double octal code 16 is used to designate "prefix prefix" code 16, which means that the code which follows immediately thereafter is a function code and will be sensed by the decoder to cause the required function to occur. The prefix code 21, shown in FIG. 9, represents the horizontal reset code whereas the function code 01 represents the set horizontal memory code. The four digits which follow the set horizontal memory code 01 are used in storing the horizontal space memory into the horizontal control circuit. The function code 34, is a write character code, and the codes which follow thereafter will be codes to select the character which will ultimately be displayed on the face of the cathode-ray tube.

FIG. 10 is a block diagram of the entire phototypesetting system described with reference to FIG. 8, and represents the same components illustrated in FIG. 8, but in greater detail. In addition, various components within the horizontal control circuit are labeled and the outputs of these components are shown connected to other circuits which control the horizontal and vertical deflection of the beam in the cathode-ray tube. The various components shown in this block diagram are later explained in detail.

OPERATION OF THE BUFFER MEMORY

The output of the control record is transferred through a buffer memory and control circuit to the decoding circuit where the information contained thereon is converted into signals for selecting the characters for display or signals which indicate that certain functions are to be performed by the cathode ray tube typesetting system. It is understood that the control record may either be the direct output of a computer or it may be control information recorded on a magnetic tape, such as described in this specification. The buffer memory and control circuit controls the operation of a magnetic tape transport since the utilization rate of the system is not constant, but varies according to the function being performed by the machine. In order to achieve the highest practical transfer rate of information, while at the same time maintaining high-density storage of information on the magnetic tape, the magnetic control tape is caused to transfer an entire block of information into the buffer memory before stopping. The more information that can be carried by one block on the control tape, the faster will be the transfer rate of that information into the buffer memory.

In the buffer memory circuit 112 constructed according to this invention, the information stored on the magnetic tape is transferred into the decoding or utilization circuit at the optimum rate. This is accomplished by storing temporarily the information contained in the tape 110 on delay lines and then using or reading out that information at the required utilization rate.

In the preferred embodiment of this invention, a magnetic tape 110 having seven channels is used to store both character and function information in a double octal code. The double octal code requires only six channels, while the seventh channel may be used for a parity check. Each of the codes recorded on the tape are separated in time by approximately forty microseconds. The information is also stored in blocks of 516 codes. There is a gap of approximately three-quarter inches or 20,000 microseconds separation on the tape between blocks of information. The first four codes in each block provide a numerical index which is used in this embodiment to identify that block for future reference. The remaining 512 codes may be used by the system either to print characters or to perform certain functions within the CRT phototypesetting system.

A block diagram of a buffer memory circuit found workable in combination with the phototypesetting system of this invention is shown in FIGS. 11A and 11B. In operation, a magnetic tape 110 is read by a magnetic head 111 containing seven magnetic pickups, the outputs of which are amplified and applied into the first register in the input register 126. While each register in the input register 126 is shown only as a single block in the block diagram in FIG. 11A, the first input register actually consists of seven multivibrators of flip-flops each having an input connection to one of the magnetic pickups in the tape reader through individual amplifiers (not shown). Information from the tape will be recorded in the flip-flops comprising the input register when a triggering pulse is applied to the first register on line 127. At the same time, the first four inputs from the tape reader are applied to the four flip-flops in the block counter register 128. Each of the seven lines from the tape reader are also connected to an OR-gate 129, the output of which provides a pulse whenever any one of the magnetic pickup heads senses a code on the tape. This pulse will be referred to in this description as the transport clock pulse. Therefore, for each code recorded on the magnetic tape, there will be a corresponding transport clock pulse when that code is read by the tape reader.

The magnetic tape is coded with an identification signal at the beginning of each block of information to enable the operator to select that portion of the tape which is to be displayed by the cathode-ray tube. This permits several different typesetting operations to be recorded on a single roll of tape and aids in the rapid selection and location of the information which is to be printed.

A particular block of information on the tape may be identified by reading the first four channels of the first four codes on the tape. This identification is accomplished by inhibiting the recordation of the information into the first four channels to the block counter register 128. The transport clock pulse is then applied through gate 131, shown at the upper left in FIG. 11A, into the transport clock synchronizer 132 for each character passing under the pickup heads. This applies a pulse to the four bit counter 133 whose output on line 134 inhibits more than four codes from entering registers 128. Once this information is recorded in registers 128, the four bit counter 133 will apply an enable signal on line 134 to the preselector coincidence control 136 to terminate the reading in of the first four channels to the block register 128 and thereafter to enable the input register 126 to receive the remainder of codes on the tape.

At this point, it should be pointed out that two modes of operation for the tape transport control are possible. It may be desired for either cause the tape to be read sequentially, without regard to the numerical block identification information contained within the first four codes, or it may be desired

to cause the tape to be scanned until a particular preselected block of information, as identified by the information in the first four codes, is to be read. For purposes of explanation, it will be assumed that a particular preselected block is to be read. In order to determine when this block starts to pass through the tape reader, the thumbwheel preselector 140 has a set of 16 binary outputs which corresponds to the decimal number indicated by the thumbwheel. When there is a coincidence between the binary outputs from the thumbwheel preselector 140 and the binary outputs from the block counter register 128, an enabling signal will be applied on line 141 to the preselector coincidence control 136. (In the event sequential operation is desired, the preselector switch 142 would be placed in the sequential position and a permanent enabling signal would then exist on line 141.)

On the occurrence of enable signals on both line 134 and line 141 to the preselector coincidence control 136, indicating that the desired block is now present in the tape reader, an enable signal will be applied on line 144 to one input of AND-gate 145 and AND-gate 146. The next clock transport pulse applied through gate 131 and the clock transport synchronizer 132 on line 147 will cause an output on line 127 from gate 146 to the character indicator register 150 and the input register 126. As will be explained, this causes the information on the tape to be transferred into the input register 126.

As long as characters are being read by the tape reader and clock transport pulses are being applied through gate 131, there will be no output from the end of block transport (EOBT) detector 152. The EOBT detector 152 senses when there is a gap of more than 120 microseconds between codes on the tape. In fact, the EOBT detector 152 will apply an enabling signal approximately 1700 microseconds after the last code has been read by the tape reader into the gate 145 causing an output on line 153 to be applied to the transport stop and start control 155. With the inhibit signal on line 153, the tape transport will stop and remain in this condition until an enabling signal is applied on line 156 and a starting pulse is applied on line 157 from the master counter 158. The enabling signal on line 156 is obtained from the time delay pulse generator 160 which provides a sufficient time delay to allow all information which has been transferred into the buffer memory to be stored before permitting the next block of information to be fed into the input register 126. The exact purpose for this time delay will be understood more completely as the explanation of the operation of this invention progresses.

While the information from the tape is applied to the first input register, this input register will not store the information until a pulse is applied to the register on line 127. As explained before, this pulse occurs for each transport clock pulse after the four bit counter has transferred the first four codes into the block counter register 128. Thereafter, all transport clock pulses will be applied through the gate 146 on line 127 to both the input register 126 and the character indicator register 150. The data stored on any register in the input register 126 will be automatically transferred to the right, to the last empty register. This function is accomplished by the character shift control 162 and by the character indicator register 150. The first indicator register or flip-flop 163, for example, indicates whether a code is stored in its corresponding register and will be in a set state when information is stored in the input register 164 located immediately above it. Therefore, for the first code to be stored, a clock transport pulse will set the information from the tape transport into the input register 164, and at the same time set the indicator register 163.

The status of the individual flip-flops in character indicator register 150 is sensed by the character shift control 162 which determines first if the register 165 is empty. If so, a shift pulse will be applied on line 166 to store the information now in register 164 into register 167 and at the same time register the indicator register 163. The character shift control then senses the condition of flip-flop 168 to determine if register 169 is empty and if so, will transfer the information in register 167

into it while at the same time resetting the indicator register 165. In like manner, all the information stored in the input register 126 will be transferred to the right until the last empty right-hand register is filled. In the preferred embodiment of the invention, it takes in the order of 5 microseconds to transfer the information from the left-hand register 164 into the right-hand register 170. It can be seen, therefore, that there is adequate time to transfer the codes into the right-hand register since the time between the codes received from the magnetic tape is in the order of 120 microseconds.

The information stored in the input registers may be considered to be stored in parallel form. This information is converted by the buffer memory circuit into a series of pulses and stored in a set of delay lines after which it can be reconverted from serial to parallel form, stored in an output register and then it is transferred into the decoder as it is needed. The output from the last register 170 in the input register 126 is applied to sampling gates 171 (FIG. 11B). When the sampling gates 171 are enabled, the information that is contained in parallel form in the register 170 (FIG. 11A) is converted into a series of pulses and applied to the delay line 172 (FIG. 11B). In the apparatus constructed according to this invention, it takes about 3 1/2 microseconds to transfer one code into a series of pulses.

To determine accurately the position of the beginning of each code in the delay line, a master control counter 158, shown at the upper right in FIG. 11A, is provided and is used to synchronize the entire buffer memory system as well as the decoder circuit shown in FIG. 12. The master counter 158 provides a pulse at the beginning of each input block through a buffer 175 and out on line 176 to the 163-microsecond counter 177, and 1,793-microsecond counter 178 (FIG. 11B).

The pulse applied on line 176, which starts the timing sequence, will be referred to in this dimension as T_{IM} . When the T_{IM} pulse is initially applied to the input of 163-microsecond counter 177, it begins the timing cycle of that element. It will be noted that this counter will apply a pulse on line 181 to the character sensor 182 (FIG. 11B) each 163 microseconds, and that initially, the eleventh pulse output from this timer is in synchronism with the T_{IM} pulse from the master counter. Each 11th pulse will be designated herein as T_1 .

The character sensor 182 controls the parallel to serial converter shift register 184. When the shift register 184 is enabled, an enabling signal on line 186 to the sampling gates 171 will cause the information stored on input register 170 to be applied to delay line 172 in a serial manner. At the same time, a pulse on line 187 from shift register 184 is applied to the character shift control 162 (FIG. 11A) to cause each of lines 166a through 166e to pulse in sequence and cause the information stored in one register in the input register 126 to transfer to the right and into the next succeeding register. An enable level is applied on line 185 (FIG. 11B) to the shift register 184 when there is a coincidence of enabling signals on both input lines 190 and 181 to the character sensor 182. An enable signal is present on line 190 if a code is stored in the last input register 170 as evidenced by the state of the character indicator register 192. As previously noted, these indicator registers will be in the set state if their corresponding input register contains a code. An enabling level will be placed on input line 181 from the 163-microsecond counter 177 each 163 microseconds.

The character sensor 182 (FIG. 11B) is turned off when there is a coincidence of signals on input line 193 and 187 indicating that all the information contained in the input register 126 have been converted to serial form. Input line 193 senses the state of the character indicator register 194 (FIG. 11A) and determines whether a code is stored in the corresponding input register while input line 187 is connected to the shift register 184. When the last code is transferred from input register 195 to register 170, the character indicator register 194 will reset and remove the enabling signal to the input line 193 of the character sensor 182 (FIG. 11B). At the same time that

the code is read out from the input register 170, a signal on line 187 from shift register 184 will be applied to the input of the character sensor 182.

During the time that the sampling gates 171 are reading the information stored in the input register 170 onto delay line 172, a signal is also applied from output 196 of the character sensor 182 to the 163-microsecond delay line 172 (FIG. 11B) to open the delay line and allow it to receive the information now being presented to it from the sampling gates 171.

Delay line 172, in the preferred form of the apparatus constructed according to this invention, is an approximately fifteen foot length of wire connecting a pair of electrical-mechanical transducers. A pulse applied to the transducer at one end of the wire will be received by the transducer at the other end of the wire after a delay of exactly 163 microseconds. The output may then be fed back into the input through a switching flip-flop to cause the pulse to be recirculated in the delay line. A signal on line 196 will cause the path to be broken and will allow information to be fed into the delay line from sampling gates 171 where it may then circulate until it is read out by the following circuits.

The position with respect to time of the coded character information stored in the delay line may be determined by the difference in time between the T_{IM} pulse from the master counter 158 and the output pulse on line 181 from the 163 microsecond counter 177. The operation of counter 177 is delayed by an amount of time equal to the time required to transfer the information stored in the input registers 126 into the delay line 172. During the time it takes to read out serially the information stored in the input register 170, counter 177 is delayed by an inhibit signal on line 199 from the character sensor 182.

Assuming two codes only are stored in the input register 126, these codes will be present in the input registers 195 and 170 and their presence indicated by enabling signals on lines 190 and 193 from the character indicator registers 192 and 194. Upon the occurrence of a T_{IM} pulse from the master counter 158, a single pulse will be applied on line 181 from counter 177 to the character sensor 182, and initiate the transfer of information from the input register 170 to the delay line 172. When the first code is read, a pulse will be applied from the shift register 184 on line 187 to transfer the information from input register 195 to input register 170. When the second code is read, a second pulse will be applied on line 187 to the character shift control 162 and at the same time to the character sensor 182. Since there is now no signal from the character indicator register 194 to input line 193 of the character sensor 182, indicating that register 195 is empty, the character sensor 182 will return to its normal state and remove the enabling signal from line 196 to the delay line 172, and from line 185 to the shift register 184.

The inhibit signal on line 199 to counter 177 is also removed at this time and this counter then restarts and continues its count by applying a pulse each 163 microseconds thereafter. However, this pulse is now delayed by the amount of time that it took to read the information on the two input registers 195 and 170 and therefore the time it takes to read fourteen bits. Since each bit is represented by a $\frac{1}{2}$ -microsecond pulse, then 14 bits would consume seven microseconds in time. The pulse therefore on line 181 to the delay line transfer control 200 is now delayed from the time T_{IM} from the master counter 158 by the time it takes the transfer fourteen bits, or time T_{14} , and will indicate when the end of the information transfer occurred into the delay line 172.

At the time T_{IM} , a pulse was also applied to the 1793 microsecond counter 178 to start its counting cycle. It will be noted that this counter counts at the same rate as the master counter 158 and has the same period as delay lines 202 and 203. In order to distinguish the pulse from the master counter 158 and that coming from each of counters 177, 178 and 179, different designations will be used for the pulse which are derived therefrom. The first pulse output from each of coun-

ters 177, 178 and 179 therefore will be designated T_1 , while the output from the master counter is called T_{IM} .

The pulse output T_1 from counter 178 will be applied on line 205 into the delay line transfer control 200. If the time T_1 on line 205 is the same as the time T_1 on line 181, it will indicate that no codes have been transferred into the delay line 172 since the output of counter 177 will be in synchronism with the master counter 158. As explained above, however, the pulse output counter 177 will be displayed in time by an amount T_{14} equal to the time occupied by the characters transferred out of register 126 into the delay line 172. As soon as the transfer is complete, the T_{14} pulse on line 181 from counter 177 will follow the T_1 pulse on line 205 into the delay line transfer control 200. Transfer control 200 will then apply an enabling signal on line 206 to cause the information in delay line 172 to be serially read into either delay line 202 or delay line 203, depending on the signal from the buffer control 175 (FIG. 11B) on lines 208 and 209.

During that time that the information in delay line 172 is being transferred into either long delay lines 202 or 203, an inhibit signal on line 210 will cause counter 178 to delay its count by an amount equal to the time occupied by the information transfer. Upon completion of the transfer of information from delay line 172 into delay line 202, the inhibit signal will be removed from line 210 and counter 178 will resume counting at T_{14} . Thus, the inputs 181 and 205 to delay line transfer control 200 are again synchronized and delay line 172 will return to its recirculating mode, having emptied the information stored therein into the long delay line 202.

When another code is applied into the input register 126, it will fill the last input register 170, as explained above, and will set the character indicator register 192 and apply an enable signal on line 190 into the character sensor 182. Upon the occurrence of a pulse T_{14} from the counter 177, which is now out of sequence with its normal synchronization with the master time by fourteen counts, the character sensor 182 will enable the shift register 184 and will cause sampling gate 171 to transfer the information from the input register 170 into the delay line 172. The delay line 172, as explained before, will accept coded information when a signal is applied on line 196 from character sensor 182. During the time that the code is being read into the delay line 172, an inhibit signal is again applied on line 205 to delay the count of the counter 178 by an amount equal to that time occupied by the code transferred, in this example, by another seven bits or three and one-half microseconds, so that the pulses are now generated by counter 178 at T_{21} .

Referring again to counter 178 (FIG. 11B), the T_{14} pulse on line 205 into the delay line transfer control 200, which is now also out of sequence with the master counter 158 pulse T_{IM} , will be applied before the T_{21} signal on line 181 is applied from the counter 177. At this time the pulse on line 205 indicates the trailing end of the information which is now circulating in delay line 202 while the pulses on line 181 indicated the trailing edge of the information which is being fed into the delay line 172. Therefore, the information representing the second code transferred into delay line 172 will be thereafter sequentially transferred into the delay line 202 after the first group of codes already contained therein passes the input.

Once the block of codes has been completely transferred from the magnetic tape 110, through the input registers 126 (FIG. 11A) and short delay line 172 (FIG. 11B) into the long delay line 202, the EOBT detector 152 (FIG. 11A) will sense the delay between the blocks of information and will apply a pulse on line 153 to stop the tape transport and also apply a pulse to the transport delay pulse generator 160. The transport delay pulse generator 160 will apply an output to the buffer control 175 after all information has been transferred from the tape to the delay lines. This is done by calculating the maximum amount of time required, under the longest possible conditions, to transfer the coded information into the delay line 202. At the end of this time, a pulse is applied to the buffer control 175 which in turn applies a signal to the output

character sensor 212 and permits the reading out of the data stored in the long delay line 202. It is noted that no read out from this delay line is possible until an entire block of codes is completely read out from the magnetic tape and stored in the delay line.

Information is read out of the long delay lines 202 and 203 only when the output register 214 (FIG. 11B) has available space to receive at least one seven digit code. The register 215 in the output register 214 forms the input to the decoder circuit (FIG. 12A) and is designated in that circuit as the first register. As the decoder accepts information from the last register 215, the character shift control 230 will be supplied with a pulse on line 216 and will cause an output on line 217 to the output register 214 and the indicating registers 218 so that the information contained in the preceding register to be transferred down so that all registers are filled. When register 220 is empty, the character indicator register 221 senses this condition and applies the signal on line 222 to the output character sensor 212. (Line 223 senses the condition of character indicator register 224.) With register 220 available, and therefore a signal on line 222, the first seven digit code in the delay line 202 may now be transferred into the output registers 214.

Before the information can be removed from the delay line 202, it is necessary to know precisely when the beginning of the information which is recirculating in that delay line passes the output. This is accomplished by starting the 1,793-microsecond counter 179 at time T_{IM} . This counter applies a pulse on line 229 into the output character sensor 212 at T_{IM} which is the same time that the codes begin recirculating in the long delay line 202. By knowing the time of occurrence of the beginning of these recirculating data pulses, it is possible to therefore read the codes out in their proper sequence. The data pulses are applied to the sampling gates 232 on lines 233 and 234 and these gates are sequentially controlled by the serial to parallel shift register 231 and transfer the data pulses on line 235 to the output register 220. The time during which the first code is read out causes the counter 179 to delay and thus indicate the beginning of the remainder of the information stored in either delay line 202 or 203.

When all of the registers in the output register 214 are full, the output character sensor 212 thereafter prevents the read out and destruction of the information in the delay line, and causes the remaining information in the delay line to recirculate. The position of this information in the delay line is sensed by controlling the counter 179 by signals on line 235. Once the delay line 202 has been emptied, the output register 214 will then accept information from the delay line 203. At this time the delay line 202 may then again receive information into its input from the short delay line 172. A continuous flow of information into the output registers is therefore maintained and may be utilized at the rate required by the decoder circuit 113 (FIGS. 12A and 12B), while the buffer memory accepts information at the design rate from the magnetic tape.

OPERATION OF THE DECODER CIRCUIT

The function of the decoder circuit shown in FIGS. 12A and 12B is to receive information in coded form from the buffer memory and transfer that information to the various components circuits which comprise the cathode ray phototypesetting system. The decoder circuit is provided with control circuits which sense the operation condition of the various components in the remainder of the system, such as the photographic material leading control, the character generator, and the horizontal control circuit, and which also senses the condition in the buffer memory device to insure that a smooth and accurate flow of information is passed from the buffer to the remainder of the circuit with the result that an accurate display is presented on the face of the cathode ray tube and recorded by the photosensitive material.

As previously explained in connection with the sample of tape shown in FIG. 9, a series of codes containing character information and machine function information is first applied

to the buffer memory 112 (FIGS. 11A and 11B) and ultimately applied to decoder circuit 113 (FIGS. 12A and 12B). Each function code, or prefix code as it will be called in this description, is always preceded by a unique code labeled the "prefix prefix code" which has been assigned, in the preferred embodiment of this invention, the double octal code "16."

The prefix prefix code "16" is used to alert the decoder circuit shown in FIGS. 12A and 12B, to the fact that a prefix code immediately follows. The prefix code, in the example shown in FIG. 9, may include a Horizontal Reset Code "21," a Set Horizontal Memory Code "01" or a Write Character Code "34." Other codes, not shown in the example, may include the leading function, the indent codes, a code to distinguish between standard face and italic face characters, point size information, etc.

Referring now to the schematic drawing in FIGS. 12A and 12B, the decoder circuit 112 consists generally of a first register 215 comprising six multivibrators or flip-flops, which are the same flip-flops as the last stage 215 in the output register 214 of the buffer memory circuit (FIG. 11B). A data register 250 and a prefix register 251 are also provided. The output of prefix register 251 is applied to a pair of decoding cards 252, 253 where a signal representing the functions to be performed by the prefix code may be applied to the proper circuitry both in the decoder and in the remainder of the system. An output is also provided through output lines 255 from the data register 250 where it may be applied to several of the circuits in the remainder of the system such as the horizontal space memory, the character selection control and the leading memory.

A control circuit 256, schematically indicated within dashed rectangle in right center portion of FIG. 12B, is provided and connected to the horizontal control circuit, the leading circuit and the point size circuit, as well as the character generator to insure that information will not be fed from the decoder into these circuits as long as these circuits have not completed their previously assigned function. Means are also provided to prevent the decoder from operating in the event that the buffer memory circuit has not sufficient information stored in its output registers to complete an assigned operation.

For purposes of illustration, it will be assumed that the information contained on the tape shown and described with reference to FIG. 9 is fed into the machine. This tape will eventually cause the information stored in the three registers 215, 250 and 251 in the decoder circuit to contain the information shown in the following table to be placed in the registers in the sequence shown.

Steps	1st register (215)	Data register (250)	Prefix register (251)
1	16		
2	21	16	
3	16	21	
4	01	16	
5	10	01	21 Reset horizontal.
6	10	10	
7	26	10	01
8	03	26	01
9	16	03	01

20	16	25 (Y)	34
21		16	34
22			

Referring now to the control circuit 256 shown at the right in FIG. 12B, it will be assumed that the remainder of the system is inactive at this time so that enabling voltages will be

applied to gate 257 from the point size circuit, to gate 258 from the horizontal feedback line 591, to gate 259 from the end of character (EOC) line 378, and to gate 260 from the leading inhibit line 743. Gate 261 applies enabling pulses from a free-running pulse generator 262 to gate 260 thereby causing an output from gate 263 to be applied on line 265 to the flip-flop 266, causing that element to set and thereafter apply an inhibit signal on line 267 to gate 259 in the control circuit 256. Thereafter, no further pulses from the free-running oscillator 262 will produce a pulse output on line 264.

When flip-flop 266 is set, a positive going signal is applied from its output on line 268 to set flip-flop 269 causing that element to apply a positive signal to one of the inputs of AND-gate 270. A second input of gate 270 is enabled since it is tied to the reset output of flip-flop 271, now in the reset condition. A clock pulse applied to the third input of this gate will cause a negative going pulse to be applied to the set input of flip-flop 271, causing that flip-flop to set on the trailing edge of the pulse. In each of the flip-flops shown in this circuit, the flip-flop is designed to set on a positive signal. The clock pulses in the decoder circuit are obtained from the master counter 158 in the buffer memory circuit. Once flip-flop 271 sets, an inhibit will be applied to the second input of gate 270 to prevent further clock pulses from being applied on its output.

Assuming that buffer memory circuit is not supplying information from the delay line into the output registers 214, an enabling signal will then be available on line 272 from the output character sensor 212 (FIG. 11B). Line 272, shown in FIG. 12A at the extreme left of the page, will apply a signal to one of the inputs of gate 273 through gates 274-277. Since in this example, the double octal code "16" is the first code to be applied to the first register 215, the decoding card 280 will sense this code and apply an inhibit signal on line 281 to one input of gate 282 (step 1).

Since the flip-flop 271 is now set, a positive level is applied from its set output to both gates 282 and 273. As previously mentioned, gate 273 is provided with an enable signal as long as the buffer memory circuit permits, and the occurrence of a clock pulse on the remaining input of gate 273 from clock 158 will then cause the gate to trigger the single shot 283, thereby providing with two output signals, a positive going output on line 284 which causes the flip-flop 269 to reset, and a negative going output which is applied to OR-gate 285 which in turn causes a positive going pulse to pass through emitter follower 286 and thence through the time delay gates 287 and line 290 to trigger each of the flip-flops in the data register 250 and thus record the prefix prefix code 16 previously stored in the first register 215. At the same time, a pulse from the time delay gates 287 will be applied through gate 291 on line 216 into the buffer memory character shift control circuit to cause the characters stored in the output register 214 (FIG. 11) to advance thus placing the prefix code 21 in the first register 215 (step 2).

Once the prefix prefix code "16" is transferred into the data register 250, the prefix code "21" appears on the first register 215, the inhibit signal on line 281 from the decoder card 280 connected to the first register 215 is removed and an enable signal is thereafter applied to gate 282. On the occurrence of the next clock pulse to gate 273, the single shot multivibrator 283 is again energized and passes a pulse through OR gate 285, through time delay gates 287 to shift the prefix code 21 into the data register 250 while at the same time providing a signal to the buffer memory control circuit through gate 291 (step 3). This same pulse will now pass through gate 282 and cause flip-flop 271 to reset at this time. Just prior to this shift, however, the prefix prefix code "16" stored in the data register was sensed by the decoding circuit 293 and caused an enable signal to be applied to gate 294.

Upon the occurrence of the same pulse on line 290 which transferred the prefix code 21 into the data register 250, a pulse was also applied through line 295 and through the delay gate 296 to enable gate 294 to set the prefix prefix memory flip-flop 297. This flip-flop is included to record the occur-

rence of the prefix prefix code "16" on the data register 250 and to permit the following code to be placed in the prefix register 251. It will be observed that as soon as the next clock pulse appeared following the entry of the prefix prefix code "16" on the data register, the prefix prefix code disappeared and was replaced by the succeeding prefix code, in this case code "21." Therefore, the flip-flop 297 is necessary to record the occurrence of a prefix prefix code for future use.

A previously mentioned, a second clock pulse applied to gate 273 will be applied through the time delay gates 287 on line 290 to shift the prefix code into the data register while a pulse is applied at the same time through gate 291 to the buffer memory to advance the next character into the first register 215 which, in this example, will be another prefix prefix code "16" (step 3).

Referring again to the prefix prefix memory flip-flop 297, an enable signal is applied from the set output of this element to gate 300. It will be assumed for the purpose of this explanation that either of the storage delay lines 202 or 203 in the buffer memory circuit are not transferring information into the output register and consequently an enable signal will be available from the output of gate 277 on line 301 to gate 300 as well as to gate 273. Upon the occurrence of a clock pulse to one of the inputs of gate 300, single shot 302 will trigger and cause a reset signal to be applied on line 303 to reset prefix prefix memory flip-flop 297 and on line 304 to set the prefix flip-flop 305. In addition, an enable signal is applied on line 306 to OR-gate 285 and applying a signal on line 290 causing the information in the data register 250 to be transferred in the manner previously explained. It is particularly noted that at this time, a pulse is also applied from the output of single shot 302 in line 304 to the trigger inputs on the prefix register 251 thus causing the prefix code "21" to be recorded therein (step 4).

Prefix memory flip-flop 305 applied an enabling signal on line 307 to one input of AND-gate 308. An enable signal is present on line 310 since the codes which would cause the gate to be inhibited are not present at this time. As will be explained later, a prefix code which requires an operation other than merely indicating the existence of the prefix code will cause gate 300 to become inhibited for the time it takes to complete those operations. Upon the occurrence of a clock pulse to gate 308, a pulse on line 311 through OR-gate 312 will apply a reset pulse on line 313 to reset flip-flop 266 and to reset the prefix flip-flop 305. It should be remembered that each of the flip-flops 314, 315 and 316 are also reset at this time although these circuit elements have not been used with reference to this particular operation.

At the same time, the decoder card 253 senses a prefix code 21 in the prefix register and causes a signal to be applied through the amplifier 317 along the horizontal reset line 318 (FIG. 12B).

It will then be realized from step 4 in the above table that, at this time, a prefix code "21" is present in the prefix register 251, a prefix prefix code "16" exists in the data register 250, a code "01" will be present in the first register 215. No further operation of the device is thereafter possible since no clock pulse can pass through gate 273 since the flip-flop 271 has returned to its reset configuration on occurrence of the second clock pulse, that no clock pulses may pass through gate 300 since the prefix prefix memory flip-flop 297 is in a reset condition, and that no pulses have been applied through the gate 320 (this gate will be discussed later in the description of the operation).

Once a horizontal reset code is applied on line 318, the horizontal control circuit 116 will place an inhibit signal on gate 258 in the decoder control circuit 256 to prevent further operation of the decoder.

The decoder circuit will remain inoperative until the remainder of the circuitry indicates that the command function has been completed. This is indicated in the present example by returning an enabling signal on the horizontal feedback line 613 to gate 258. Since flip-flop 266 has already returned to its reset condition, an enabling signal is also availa-

ble on line 267, thus permitting the next pulse from the pulse generator 262 to supply the system command pulse along line 265 to set flip-flop 266. The setting of flip-flop 266 will cause the inhibit signal to be placed on the control circuit 256 and cause flip-flop 271, 269 to set in the manner previously described.

A clock pulse through gate 270 will cause flip-flop 271 to set and thereby enable clock pulses to pass through AND-gate 273, provided the buffer memory circuit is not transferring information at this time. Since a prefix prefix code "16" exists in the data register 250, an enable signal will be applied to gate 294, and upon the occurrence of a clock pulse through gate 273 and single shot 283, the prefix prefix memory flip-flop 297 will set. The same clock pulse will cause a signal through time delay gates 287 to trigger the data register 250 and buffer memory output registers 214 through line 216, transferring a "01" code into the data register 250, and, in this example, a "10" code into the first register 215 (step 5). Since a code "16" does not exist in the first register, this same clock pulse is permitted to pass through gate 282 to reset flip-flop 271.

Since the prefix prefix memory flip-flop 297 is set, the prefix code stored in the data register 250 will be transferred into the prefix register 251 by setting the prefix flip-flop 205 at the same time that a clock pulse is applied through gate 300 and single shot 302 to the trigger input on the prefix register 251. The pulse is also applied through OR-gate 285 to trigger the input to the data register and the buffer memory to cause the information in the entire system to advance (step 6).

Since a "01" code is now stored in the prefix register 251, an enable signal will be supplied from the decoder card 252 through the OR-gate 321 along line 324 to gate 320. Since each of the inputs to this gate will be in an enable condition, a clock pulse applied to gate 320 will cause a pulse to be applied along line 325 to single shots 326 and 327.

At the same time, the signal on line 310 from gate 321 will cause an inhibit signal to be applied to one input of gate 308. So long as a code exists in the prefix register which causes an output from either of the OR gates 321, 322 or 323, gate 308 will be inhibited and clock pulses will not be permitted to pass therethrough to reset the system. The prefix memory flip-flop 305 will not reset until after the last code in the data register which necessarily follows the "01" code has been utilized by the horizontal space memory flip-flops in the horizontal control circuit.

The output of single shot 326 will then be applied on line 330 to gate 331 as well as the trigger inputs of AND-gates 332, 333 and 324, although these last mentioned gates cannot function at this time since there is an inhibit signal on each. At the same time, the output of single shot 327 will be applied through OR-gates 285 to cause the characters stored in the registers to advance, as previously explained (step 7).

Gate 331 will have an enable signal on each of its inputs and, on the occurrence of the first pulse on line 330, will cause flip-flop 314 to set. At the same time a signal will be applied along line 335 and through gate 336 to the output line 337. The other input of gate 336 will be enabled by a signal along line 340 from the decoder card 252. Thus, a pulse applied from the output of gate 336 will be applied along line 337 to set into the first set of space memory flip-flops in the horizontal control circuit the code which is at the same time existent in the data register 250 and applied to the space memory flip-flop shown in FIG. 12 along cable 255 (step 7).

Once the flip-flop 314 energizes, an enable signal will be applied on gate 332 and an inhibit signal will be applied on gate 331. As long as an "01" prefix code exists in the prefix register, the gate 320 will be enabled and the next clock pulse will be permitted to pass through this gate and along line 325 to again energize single shot 326 and cause a signal to pass through gate 332 to set flip-flop 315 and apply an enable output along line 341 through gate 342 and along line 343 to set into the second set of space memory flip-flops the information now contained in the data output lines corresponding to the information stored in the data register. At the same time that a

signal was applied to the pulse distribution flip-flops, a pulse was also applied through single shot 327 to cause the data information to advance (step 8).

In like manner, the distribution pulses will be applied from gate 344 through line 345 and from gate 346 through line 347 to set the space memory flip-flops in the horizontal control circuit. Once the last distribution pulse has been applied from single shot 348, an inhibit signal will be applied to gate 331 to prevent recycling of the distribution pulses (steps 9 and 10).

10 The occurrence of another prefix prefix code "16" in the first register (step 9) indicates that the information in the data register is the last code to be distributed to the space memory flip-flops. The decoder card 280 senses the "16" code in the first register and applies a negative output on line 281 through gate 350 and into gate 351. Another input to this gate is derived from line 330, and on the coincidence of the last distribution pulse, and the "16" code in the first register, permits a signal to pass through OR-gate 312 to reset each of the flip-flops 314, 315, 316, and to reset 266. At the same time, the prefix memory flip-flop 305 is reset completing the removal of the enabling signal from gates 320 thereby preventing any further clock pulses through this gate from being applied to the pulse distribution flip-flops.

20 The operation of the decoder proceeds with respect to space command code "10" in a manner similar to that explained with respect to the horizontal reset code "21" and causes an output from the decoder card 252 to be applied through the gate 355 to the positive horizontal space flip-flop 611 shown in FIG. 20a (steps 11 and 12).

25 With respect to the set small point size code "05," an output from decoder card 252 will be applied along line 357 through gates 360 and 361 where it will be applied on line 362 to the set point size input shown in FIG. 20a and cause the point size 35 memory flip-flop 364 to retain the information presented to the flip-flop inputs from the decoder lines 255 attached to the data register 250. Also connected to the output of 361 is a single shot 363 which places an inhibit signal on gate 257, the duration of this signal being predetermined to assume that the information in the data register has been transferred into the point size memory circuits (step 13).

30 It is noted that at the time the prefix code "05" is stored in the prefix register, and the "52" code is present in the data register, that the first register 215 contains a prefix prefix code "16" which will be detected by the decoder card 18 to prevent the resetting of flip-flop 271 (step 14). Since this flip-flop remains set, clock pulses are able to pass through the gate 273 and continue to advance the information stored in the first register 215 to the data register 250, and the information in the buffer memory to the next succeeding register, as previously explained (step 15). Once the 16 code has passed out of the data register, the inhibit is removed from line 281 and the flip-flop 271 is reset on the next clock pulse.

35 The system is thereafter reset in the following manner. A clock pulse through gate 320 will be applied in line 325 to trigger single shot 326 and pass an enabling pulse through line 330 and onto gate 351 which also has an enabling pulse thereupon from line 281 since the first register does not now contain the prefix prefix code "16." A reset pulse is therefore applied along line 313 to set the prefix flip-flop 305 and flip-flop 266. At the same time, the pulse along line 325 will trigger single shot 327 and cause the information in the system to advance to the next register (step 16).

40 Thus, the write character code "34" will exist in the data register and the "05" code will be present in the prefix register at this time. It should be remembered that since the prefix prefix code "16" did exist in the data register immediately prior to the "34" code being applied thereto, and this fact will 45 be recorded in the prefix memory flip-flop 297. The occurrence of the next succeeding clock pulse will cause the gate 300 to energize single shot 302 and thus set prefix flip-flop 305 and transfer the write character code "34" into the prefix register 251 at this time. The prefix prefix memory 297 will 50 also reset. The code "07," representing the letter M, will now 55

appear in the data register 250 while the code "30," representing the letter *a*, will appear in the first register 215. No further clock pulses through gate 300 will be possible thereafter since the flip-flop 297 will be reset. The system therefore will stop momentarily until the receipt of a system command pulse is received along line 265 (step 17).

A system command pulse will again be received along line 265 to set flip-flop 266 and flip-flop 269 and on the occurrence of the clock pulse through gate 270 to set flip-flop 271. As previously explained, gate 273 will be enabled with the set output from flip-flop 271 and, providing no inhibit signal is obtained from the buffer circuit, the first clock pulse through this gate will cause each of the codes in the registers to advance. The code "34" is detected by the decoder card 253 and a signal applied through gate 370 along line 371 to the character code generator shown in FIGS. 14 and 17, and also on line 327 to gate 373.

Since no code "16" exists in the first register at this time, line 281 will be an enable and this enable signal will be applied to gate 373. Furthermore, a code "16" does not appear in the data register and therefore the output of the code "16" detector 293 will be positive and will enable gate 374. Since flip-flop 271 will be in the set condition for the first clock pulse, an enabling voltage will also appear on the other input to gate 374. On the occurrence of a clock pulse to gate 273, a pulse will be applied to gate 373 and will apply a negative pulse through gate 312 to cause flip-flop 266 to reset. At the same time, the clock pulse will pass through gate 282 to reset flip-flop 271.

When flip-flop 266 resets, it triggers the single shot 376 which will apply the decoder write pulse on line 377 to the character generator shown in FIGS. 14 and 17 to cause a character to be printed or displayed in the face of the cathode ray tube. While the character is being written on the face of the tube, an inhibit signal will be applied on line 378 to gate 259 in the control circuit 256. Once the end of character (EOC) signal is received, another system command pulse will be created on line 265 to set flip-flop 266 and repeat the operation described above (steps 17 through 20).

Eventually a code "16" will appear in the first register 215 causing an inhibit signal to be applied to line 281 from decoder card 280 which will inhibit both the gate 373 and gate 282. It will be recalled that it was through gate 373 that the reset pulse was obtained to reset flip-flops 266 and other portions of the circuit and it was through gate 282 that flip-flop 271 was reset. Since 271 remains set, additional clock pulses may be caused to pass through 273 to continue to shift the data register 250 and first register 215 thereby advancing the information contained in these registers to the next succeeding register (Step 21). The code "16" appearing in the first register will then be sent to the data register, where it will be detected by the code "16" decoder circuit 293 and cause the memory flip-flop 297 to set in due course.

When the code "16" is replaced in the first register by the following code, the inhibit on line 281 will be removed. However, it will be observed that an inhibit signal will be applied to gate 374 from the code "16" decoder 293 on the data register 250, thereby continuing to prevent any pulse from passing through gate 274 to cause the system to reset. Consequently, another clock pulse will pass through 273, to shift the information stored in the registers to the next succeeding register (step 22). At this time, a signal will be applied through 282 to reset flip-flop 271 to prevent further pulses from being applied to the shift inputs on the registers. Therefore, the system will continue to pulse and transfer the information to the next succeeding register by the clock pulse through gate 300 and gate 285 until the next prefix is stored in the prefix register at which time a pulse through gate 282 will reset gate 271.

Provisions are also made in the decoder circuit to prevent the decoder from operating on command of the buffer memory when the buffer long delay lines are transferring information into the buffer output registers. A signal from the buffer memory on line 272 will be applied to the input of both

gates 274 and 380. Should the buffer be transferring information, an output from 274 will be applied to inhibit gate 273 and prevent clock pulses from passing through this gate as well as gates 300 and 320, thus preventing the operation of the decoder circuit for that time.

Certain codes used by the buffer memory circuit to indicate that the information in the buffer long delay line should either continue to recirculate or to be erased may also be contained and controlled by the decoder circuit. Thus, a code "35" indicates a command to recirculate, and when this code is placed into the first register 215, it is detected by the decoder card 280, energizes gate 274 to prevent the operation of the decoder, and also passes a signal down line 381 to gate 382 where it causes some circuits in the buffer memory to repeat. A delete code "32" is also obtained from the decoder card 280 which also prevents the operation of the remainder of the decoding circuit by an energizing gate 384 and at the same time passing the signal along line 385 to gate 382 and to single shot 386. These elements cause the signal in the delay line to be erased and causes the buffer memory to reset.

DECODING CARD

FIG. 13 illustrated a typical decoding card or circuit which may be used to translate the information stored on the data register and to an electrical signal usable by the remainder of the typesetting system. In addition, this circuit may also be used to function either as a NOR gate or an AND gate, and is similar to such gates used in the decoder circuit, the buffer circuit and the horizontal control circuit.

Two transistors 390 and 391 are provided with the collector and emitter elements of each connected in parallel. The power supply voltage of -6 volts is applied to terminal 393 through a collector load resistor 394 to the collector element of each transistor. The transistors are normally biased at cutoff by a voltage divider network including a source of positive voltage, in the order of +6 volts supplied to terminal 395, and resistors 396 and 397. The base electrode of each transistor is connected to the junction between the resistors 396, 397. Four inputs are provided to each transistor through input terminals 400 which are connected to the base electrode through an isolation resistor. The input terminals 400 are normally at ground potential when the circuit used as decoder circuit and the gate is caused to function upon the application of a -6 volts to any one of the inputs 400.

If all of the inputs to the gate are at ground potential, then both of the transistors remain in the nonconducting or cutoff state, and the voltage at the output terminal 401, which is controlled directly to the collector electrodes, will assume the input supply voltage on terminal 393, or -6 volts. However, if -6 volts is applied to any one of the inputs 400 connected to the base of either transistor, that particular transistor will conduct, and the voltage on both collector electrodes will decrease effectively toward ground potential. In other words, a zero-volt output will be available if the -6 volts signal is applied through the input resistor to the base electrode of either transistor causing it to conduct.

As will be apparent to those skilled in the art, this gate may not only function as one of the decoder circuits attached to the data register 250 in the decoder but may also be considered as an AND gate requiring that all of the inputs assume zero volts if the output is to be -6 volts, or it may be considered a NOR gate which accomplishes the function of providing a zero volt output if any one of the inputs assumes a -6-volt level.

CHARACTER GENERATOR OPERATION

Referring now to the block diagram of the character generator shown in FIG. 14, it will be seen that the character generator 114 includes a character disc 41 rotated by a motor 415 and illuminated on one side by a set of lights 416. A set of photomultiplier tubes 417 common to all bands on the character disc is also provided. A set of fiber optic light trans-

mission fibers 420 are provided so that each photomultiplier observes the pattern on one track in each band recorded on the disc. It will be remembered, that in the typical disc construction according to this invention, that each band contains 35 tracks, with 32 of these tracks recording character information. It is therefore necessary that a single photomultiplier tube be reserved to sense the information on each track recorded on the character disc 41.

On command from the decoder, the binary number representing one band on the character disc 41 is decoded and causes a shutter (not shown) to open which allows light from all tracks in one band to fall on the fiber optics which transmits the optical signal stored in each track to the photomultiplier 417. These convert the optical signals to electrical signals and pass them through the pulse forming networks 421. The synchronizing channel on the character generator disc is detected by a photomultiplier tube and the electrical signal from that tube directed through the pulse forming circuit 422, shown in detail in FIG. 15, the output of which insures that the pulse directed into the character generator raster and Z-axis control circuit 423 is of sufficient duration and magnitude to cause reliable operation of the circuit.

Referring briefly to FIG. 15, the input 424 to the pulse forming circuit 422 is connected through a capacitor 425 to the photomultiplier tube 417 monitoring the synchronizing channel. The operation of this pulse forming circuit is conventional and will not be explained in detail. The output of the pulse forming circuit 422 is taken from the collector of transistor 426 on line 427 and applied into the character generator raster and Z-axis control circuit 423. The pulse forming circuits 430 and 431 connected to the photomultiplier tubes monitoring the fiducial and up-down channels on the disc 41 are similar to the circuit shown in FIG. 15, except that these circuits are not capacitively coupled as in the synchronizing channel.

The pulse forming circuits 433, one of which is shown in FIG. 16, are connected to each of the photomultiplier tubes monitoring the marks on the character tracks in each band on the character generator disc and include, in addition to the normal pulse forming circuit, a selection circuit connected to cable 255 from the output of the data register 250 in the decoder (FIG. 12A). Thus, upon the occurrence of the proper code on the data register 250, the output of one of the pulse forming circuits 433 will be opened and the pulse applied to the input 434 from the photomultiplier will be allowed to pass into the character generator raster and Z-axis control circuit.

Also included in the character generator circuit 114 is the character generator raster and Z-axis control 423 which utilizes all of the signals obtained from the character generator along with the signals obtained from other circuits to be later described and which applies a variable voltage on the deflection coils of the cathode ray tube to form a character thereon in a raster type fashion. The variable voltage output from the character generator is described in other prior art devices of this type as the minor deflection voltage. Other circuits, which will be described in detail later, provide a major deflection voltage which may be defined as that voltage which positions horizontally the entire character on the face of the cathode ray display tube.

The output of the synchronizing pulse forming circuit 422 is used to trigger a set of flip-flops connected in series and controls the vertical position of the cathode ray tube beam. The synchronizing pulses are also used to gate on the cathode ray tube beam and thereby form a series of equally spaced dots generated at the rate determined by the synchronizing pulses and separated vertically a distance determined by a voltage input to the character generator raster and Z-axis control circuit from the reed relay shown in FIG. 24.

One channel on the character disc is designated as the up-down channel and controls the vertical direction of travel of the cathode-ray tube beam. Each time a change in direction of the up-down signal occurs, the electron beam in the cathode-ray tube will be moved horizontally a predetermined distance

in response to the output of a series of six toggled flip-flops triggered by the up-down signal. These toggle flip-flops in turn control in a series of steps the voltage output of a horizontal digital to analogue (D/A) circuit which supplies the minor horizontal deflection signal to the cathode-ray tube. The input voltage to this horizontal D/A circuit is obtained from the reed relay circuit which determines the ultimate size of the character displayed.

10 A third input from the character generator disc is designated as the fiducial input and is used to insure that the selected character is displayed on the face of the cathode-ray tube only after a fiducial mark on the character disc has passed the associated photomultiplier tube. By this means, the generation of the character will be started only at the beginning of the recordation of that character on the character disc.

15 The other photomultiplier tubes and associated pulse forming circuits receive the character information itself from the character disc. This character information determines when the cathode-ray tube beam is to be turned on. Thus, the character signal will be applied to control the Z-axis or the intensity modulation on the cathode-ray tube. The character signal also includes an end of character (EOC) signal which 20 will occur only when the cathode-ray tube beam is in its lowermost position.

25 The character generator and Z-axis control is also provided with a 2x point size input from flip-flop 364 in the decoder (FIG. 12B), and is used in part to control the size of the 30 character generated.

When an input is provided on line 371 from the decoder to 35 initiate character generation, the character generator and Z-axis control will in turn supply an inhibit signal on line 378 to the decoder circuit to prevent the further operation of that device until after the character selected has been completely formed on the face of the cathode-ray tube.

Referring now to FIG. 17, which shows particularly the character generator raster and Z-axis control circuit 423, the synchronizing signal from the character disc is applied on line 427 to trigger a single shot multivibrator 450 which in turn pulses the input to the parallel gated counter 451. The outputs of this counter are connected to the vertical D/A circuit 452. This circuit, the details of which will be explained with reference to FIG. 23, provides an output voltage which is dependent upon the status of the flip-flops comprising counter 451 and the voltage applied to the circuit from the point size determining reed relay circuit (FIG. 24). The synchronizing pulses are also applied along line 453 to one input of gate 454 for gating the cathode ray tube beam, and to gate 455 which is a part of the end of character (EOC) signal generating circuit. The up-down signal from the pulse forming circuit 430 is applied on line 457 to the input of the counter flip-flops 458. These flip-flops have their outputs connected to a horizontal D/A circuit 459 to provide the minor horizontal deflection voltage applied to the cathode ray tube.

Interconnections between the up-down signal and the vertical counter 451 are also provided through single shot multivibrators 460 and 461 to insure that, on the occurrence of an up signal, all of the flip-flops in the vertical counter 451 are reset to place the cathode ray tube beam in its lowermost position. In the same way, upon the occurrence of a down signal, all of the flip-flops in counter 451 are placed in the set condition so that the vertical D/A circuit 452 places the beam in its uppermost position. In this way, the position of the beam at at least two positions is positively controlled.

Upon receipt of a fiducial signal on line 463 from the pulse forming circuit 431, a reset pulse will be applied to reset the horizontal flip-flops 458 thereby assuring that the cathode ray beam is at its extreme left hand position with respect to the raster pattern to be formed. At the same time, the artificial end of character flip-flop 466 will be reset.

With all of the horizontal flip-flops 458 in the reset position, the first up-down signal to be received from the character disc 75 will cause the first of these flip-flops to trigger and to alter the

voltage output from the horizontal D/A. Thereafter, for each change in direction of the scanning beam as indicated by the up-down signal, there will be a change in the state of the voltage on line 457, thus causing the horizontal step flip-flops to step and move the beam horizontally one incremental unit.

When a write character code "34" has been stored in the prefix register 251 in the decoder (FIG. 12A), an enable signal will be applied on line 371 to gate 470, shown at the lower left in FIG. 17. When the decoder has completely transferred the first character code into the data register 250, an enable pulse from the single shot 376 (FIG. 12A) will occur, the duration of which is sufficiently long that at least one fiducial signal from the character disc and this pulse will be applied on line 377 through gate 471 (FIG. 17) to set the flip-flop 472 if no fiducial signal exists into gate 470.

On the coincidence of the character code signal on line 371 to gate 470, the absence of a fiducial signal on line 463, and assuming that the end of character output line 473 also provides an enable signal to gate 470, the occurrence of the decoder write pulse on line 377 will cause gate 471 to set flip-flop 472. This flip-flop is designed to set at the end of the decoder write pulse on line 377. Once flip-flop 472 sets, an inhibit signal will be applied on line 378 to the decoder (FIG. 12B) to inhibit the operation of the decoder until an end of character signal is created on line 473.

With flip-flop 472 in the set state, an enable signal is applied on line 475 to gate 476. The next fiducial signal available on line 463 will pass through gate 476 and cause the flip-flop 477 to set. This last mentioned flip-flop applies an enable signal on line 478 to one of the inputs of gate 454. As has been explained, another input to the gate 454 is enabled at each synchronizing pulse on line 453. A third input to gate 454 is controlled by a NOR-gate 480 which comprises gates 481, 482 and 483. Gate 480 produces an output if the counter 451 is in the reset state and if simultaneously character information exists on line 485. The output of gate 480 on line 487 is the end of character pulse as it detects the specific conditions for this pulse. At other times, gate 480 allows the operation of gate 454. The remaining input to gate 454 is applied on line 485 from the pulse forming and selection circuit 433 from the character track in the character generator which has been previously selected by the decoder circuit. Thus, upon a coincidence of signals from the synchronizing input 427 and from the character signal input 485, an output will be available from gate 454 on line 486 to gate on the cathode ray tube beam.

The width of the character displayed on the cathode ray tube in this embodiment of the invention may be determined by the number of up-down pulses required to trace the character in a raster type pattern. Each time the beam is caused to move horizontally one step, a horizontal step pulse is applied into the precounter circuit 524 (FIGS. 10, 20 and 21A) in the horizontal control circuit to store that width information so that the initial starting position of the beam for the next character may be accurately determined. For reasons of timing and to insure reliable operation of the counting circuits, the horizontal step pulse which indicates the width of the character being presented is created only after the beam has started its trace.

In the preferred embodiment of the invention, a single horizontal step pulse occurs when the beam has moved vertically 24 steps out of the possible 64, if the 2x flip-flop 364 (FIG. 12B) is in the reset state. If the 2x flip-flop 364 is in the set state, two horizontal step pulses occur at counts of 24 and 28 out of a possible 128 steps. These two pulses are necessary for proper width calculations for larger point sizes. For this reason, the input to NOR-gate 490 (FIG. 17) is connected to the outputs of the flip-flops in the vertical counting flip-flop 451 counting the 8, 16 and 32 steps. The connection is so arranged that upon the occurrence of a twenty-four count in the vertical step flip-flop 451 (assuming 2x flip-flop 364 is reset), gate 490 will be enabled for eight counts and a horizontal step pulse will be applied on line 412 to the horizontal control circuit shown in FIG. 21A.

Referring briefly to FIG. 18, the voltage level on the up-down line 457 (FIG. 17) is shown in FIG. 18 at A while the voltage output from the vertical D/A 452 on line 411 is shown in FIG. 18 at B. The horizontal voltage on line 410 from the horizontal D/A 459 to the cathode ray tube is shown in FIG. 18 at C. The occurrence of the horizontal step pulse is also indicated in FIG. 18 at D. At the time the up-down signal on line 457 changes, the flip-flops in the vertical counting circuit 451 will assume their full counting state so that the beam in the cathode-ray tube always starts from a reference position even though an error in the counting of the pulses in the vertical flip-flop 451 may have occurred for any reason.

Referring again to FIG. 17, the end of character signal (EOC) will occur when the vertical counting flip-flops are in the full lowermost counting state and an enable input is applied from each of the flip-flops to gate 480. An end of character signal will be received on line 485 from the character generator disc at the same time that an enable signal is available on the remaining inputs of gate 480. Accordingly, an inhibit signal will be placed on gate 454 to prevent the writing or display on the face of the cathode ray tube of the end of character signal, and at the same time an enable signal will be applied to gate 455 and to reset flip-flop 477. When flip-flop 477 resets, the enable signal to another input of gate 454 will be removed and no further pulses applied to that gate will cause the cathode-ray tube to be illuminated. A reset signal is also applied on line 493 to reset flip-flop 472, and an end of character signal will be applied on line 473 if the character raster has an even number of vertical scan lines.

If the character raster has an odd number of scan lines, an end of character signal applied on one input of gate 455, and a synchronizing signal applied to the second input of that gate, and assuming that an enable signal is also applied on 494 from the up-down line 457 affirming that the scan is in the up direction, gate 455 will be enabled when the single shot 495 is initiated by the resetting of flip-flop 477. Gate 455 in turn energizes a single shot 496 and supplies a pulse along line 473 into the horizontal control circuit and will at the same time apply an additional pulse through gate 497 onto line 412 to the horizontal step input of the horizontal control circuit.

An artificial end of character pulse is also available from flip-flop 466. Proper functioning of the system requires that an end of character signal be supplied at the termination of the character generation operation. Otherwise, the operation of the decoder and the horizontal control circuit will be inhibited. To provide this signal in the event that the normal end of character signal fails, a system is provided whereby the occurrence of a fiducial signal on line 463 will reset flip-flop 466 and cause a pulse to be applied on line 498 to reset flip-flop 477, and thereby supply the end of character pulse through gate 497 in the same manner as previously described.

The size of the characters displayed on the cathode ray tube will be regulated by the magnitude of the voltage applied to both the horizontal D/A circuit 459 through line 620a and to the vertical D/A circuit 542 through line 630a. The voltages on these lines are supplied from the reed relay circuit shown in FIG. 21 and are dependent upon the commands on the control tape 110 which are set into the point size memory circuit 523 (FIGS. 10 and 20A). Thus, with the ultimate size of the character determined by the voltage on lines 620a and 630a, the character may be created in a raster type fashion by modifying this voltage through the action of the counter flip-flop 458, thereby controlling the horizontal position of the beam, and through the action of counter flip-flops 451 to control the vertical position of the beam.

FIG. 19 shows the change in size of the letter "A" as a result of a change in voltage applied to the minor deflection horizontal and vertical D/A circuits. Both the nine point letter and the five point letter are generated from the same track on the character generator disc and have the same number of lines forming the letter, the only difference between the two letters being in the magnitude of the horizontal and vertical size voltages applied on lines 620a and 630a.

The 2x point size memory line 499 (FIG. 17) is connected to the decoder circuit and applies an input to the vertical D/A circuit 452 normally when a character is generated having 64 vertical lines. When a character requires 128 vertical lines. The signal is removed from line 499 and the 128-count flip-flop in the vertical counting circuit 451 then supplies the necessary count to the vertical D/A 452.

It is also possible to create an oblique type character by modifying the voltage applied to the horizontal deflection coil as a function of the voltage applied to the vertical deflection coil. This is accomplished in the present embodiment of this invention by including an oblique digital to analogue circuit 502 (FIG. 17) having an input controlled by the vertical flip-flops 451 and having the size voltage obtained from the horizontal line 620a. Thus, as the character is traced vertically upwardly, the horizontal voltage is modified by a proportionate amount. A relay 503 controls the voltage applied to the horizontal output line 400, and the position of this relay as determined by the status of the flip-flop 504 determines whether or not the voltage output of the oblique D/A circuit 502 will be added to the horizontal deflection line 410. The flip-flop 504 is connected directly to the decoder through lines 505 and 506.

Accordingly, the character generator described above utilizes the information stored on a spinning character generator disc to generate a character on the face of a cathode-ray tube in a raster-type fashion. The character is selected by a signal from the decoder, and the character is caused to be displayed on a further signal from the decoder. During the time that the character is being generated, the decoder is inhibited from other operation. The size of the character displayed will be dependent upon other information stored in the system, and particularly upon the status of a point size memory in the horizontal control circuit, the details of which will be described later.

While an optical character disc has been shown and described as the preferred means for the character generator, it is to be understood that other optical means for storing the digital character and control signals may be used without departing from the scope or spirit of this invention. Such other optical storage means could include a transparent rotating drum or a transparent tape onto which the optical signals representing character and control data are recorded.

It is further contemplated that character generating means other than the optical means described herein, such as a magnetic memory device, could be used with the remainder of the typesetting system herein described as long as a first set of signals representing the characters and a second set of signals for positioning the beam of the cathode ray tube are retained. A magnetic character generating means could therefore include one or a plurality of magnetic discs functionally similar to the optical disc described herein, but with the digital signals spaced sufficiently to eliminate cross talk, or it could include the storage of the digital signals in the magnetic memory of a computer, such as a core memory or magnetic tape.

OPERATION OF THE HORIZONTAL CONTROL CIRCUIT

The horizontal control circuit 116 shown in FIGS. 10, 20 and 21A through 21D functions to control the position of the cathode ray tube beam prior to the generation of each character on the display face of the cathode ray tube in response to commands supplied to it from the decoder circuit (FIG. 12) and in response to width information obtained from the character generator (FIGS. 14 and 17).

Referring now particularly to the simplified block diagram of the horizontal control circuit shown in FIG. 20, information from the decoder circuit shown in FIG. 12 and from the character generator circuit shown in FIGS. 14 and 17 is supplied to the horizontal control circuit. The information obtained from the decoder determines in part the size of the character being generated and the interword spaces thus allowing justified lines of type to be created. The information

supplied to the horizontal control circuit from the character generator is used in conjunction with the information supplied from the decoder with regard to the size of the character to determine the intercharacter spaces and to reposition the beam after the character generating operation is completed in preparation for the generation of the next character.

A space memory circuit 520, consisting of a set of storage multivibrators or flip-flops, is connected to receive information regarding interword spaces from the decoder circuit. In a preferred embodiment, the flip-flops in the space memory are so connected to the decoder that they receive the space information contained therein only upon the receipt of an additional signal from the decoder, herein called a distribution signal which causes that information to be stored in the space memory.

An indent memory 521, similar in construction and operation to the space memory 520, is also provided. The indent memory actually senses the information stored in the space memory and will accept that information only upon a distribution signal from the decoder on line 522. Thus, the information which is stored in the indent memory must first be recorded in the space memory and then transferred into the indent memory upon a further distribution signal from the decoder.

The horizontal control circuit 116 is also provided with a point size memory 523 which receives the information from the decoder circuit on cable 255 and stores this information as a multiplier indicating the size of the characters subsequently to be generated.

The character generator (FIG. 14) supplied a horizontal step pulse on line 412 to the precounter circuit 524 in the horizontal control circuit 116 each time the cathode-ray tube beam moves horizontally one step in the generation of a character. For each horizontal step pulse, the point size information stored in the point size memory 523 is transferred into the flip-flops which comprise the precounter 524. Therefore, the number of horizontal step pulses is in effect multiplied by the value of the point size as recorded in the point size memory. The output of the precounter is applied to the storage counter 525.

The storage counter 525 is connected to the interpolation counter in such a manner that the information contained in the storage counter may be transferred directly to the interpolation counter upon the completion of the generation of a character as indicated by an end of character (EOC) signal. The information stored in the space 520 and indent memory 521 may also be transferred into the interpolation counter 526 by an appropriate command from the decoder.

The status of the main counter 527 may be altered by the output from the interpolation counter 526 or by transferring information upon a command from the decoder from either the space memory 520, the indent memory 521, or the storage counter 525. The output of the main counter 527 is used to select one of 64 major horizontal deflection digital to analogue (D/A) circuits, each of which supplies a first major horizontal deflection voltage and focus voltages for the cathode ray tube in a particular horizontal increment. The details of the operation of these 64 horizontal D/A circuits will be described hereinafter.

The output of the interpolation counter 526 is connected to a single horizontal D/A card used to supply a second major horizontal deflection voltage to the cathode-ray tube. The voltage supplied to this single circuit is derived from the selected one of the 64 horizontal D/A circuits as controlled by the main counter 527 and is divided into 64 increments with the voltage output determined by the status of the interpolation counter. Therefore, the display face of the cathode-ray tube is first divided into $\frac{1}{8}$ -inch increments with these $\frac{1}{8}$ -inch increments further divided into 64 smaller increments by the operation of the interpolation counter. A least significant digit counter 528, the status of which is controlled by the precounter 524, is also provided to act with the interpolation counter to make small variations in the major horizontal deflection of the beam.

Referring now to FIGS. 21A through 21D for a detailed description of the horizontal control circuit, the space memory 520 includes seventeen flip-flops which have their inputs connected to a cable 255 leading to the data register 250 in the decoder circuit shown in FIG. 12A. The space memory flip-flops are divided into four groups with the first group consisting of five flip-flops and the remaining three groups containing four flip-flops each. The first group of flip-flops, including flip-flops 520a through 520e have their inputs connected to ten of the 12 available input lines of cable 255. The flip-flops in the other three groups are connected to eight of the available lines in cable 255. Flip-flops 520a may be connected to the same pair of lines as flip-flops 520f, 520j and 520n, while flip-flop 520b may be connected to the same pair of lines as flip-flops 520g, 520k and 520o. Thus, most of the input lines in cable 255 from the decoder have more than one flip-flop connected thereto. However, the flip-flops connected to these lines will only accept the information presented thereon when a distribution pulse from the decoder is applied.

The flip-flops of the first group, including flip-flops 520a through 520e, receive a distribution pulse from the decoder on line 337 when a set space memory signal is present in the control tape (see FIG. 12B). This distribution signal enables each of the AND gates connected between the inputs of each flip-flop and the cable 255 and allows the space information in cable 255 to be stored by the flip-flops. In like manner, the space memory flip-flops 520f through 520i, 520j through 520m, and 520n through 520q, may receive the distribution pulses from the decoder on lines 343, 345 and 347, respectively.

The indent memory 521 also includes a set of seventeen flip-flops with the inputs thereof connected to the outputs from their respective space memory flip-flops, shown in FIGS. 21A through 21D, immediately thereabove. Thus, the indent memory flip-flops may record the information stored in the space memory flip-flops 520 when a distribution pulse from the decoder is applied on line 522. This distribution pulse enables one input to each of the AND gates which are located in the input circuits of each of the indent memory flip-flops.

The five flip-flops which comprise the point size memory 523 also have their inputs connected through AND gates to cable 255 and to the output of the data register 250 shown in the decoder circuit shown in FIG. 12A. These registers or flip-flops only record the data stored in the data register 250 when a set point size signal is applied on line 362 from the data register (see FIG. 12B). This set point size signal enables the other input to the AND gates and allows the information stored in the data register 250 to be transferred into the point size memory 523.

Once the necessary information to create a justified line of type is set into the space and indent memories and information regarding the size of the characters next to be generated is supplied to the point size memory, the horizontal control circuit may then be operated to select the proper major deflection horizontal D/A circuits and control the horizontal position of the beam prior to character generation.

A precounter circuit 524 is included in the horizontal control circuit to store the product of the multiplication of the number of horizontal step pulses received from the character generator during the development of a character on the display face of the cathode ray tube by the point size of that character as stored in the point size memory 523. The point size information is transferred through a gate means 540 which interconnects each of the storage flip-flops 523a through 523e with the precounter flip-flops 524a through 524e, respectively. The gate means 540 also connects both the space memory flip-flops 520a through 520d and the indent memory flip-flops 521a through 521d with the precounter flip-flops 524b through 524e, respectively.

The gate means 540 includes a first set of AND-gates 540a, through 540e, each having one input connected to the output of the point size memory flip-flops 523a through 523e, respectively, a second set of AND-gates 540g through 540j, each having an input connected to the outputs of the indent

memory flip-flops 521a through 521d, respectively, and a third set of AND-gates 540l through 540o, each having an input connected to the outputs of the space memory flip-flops 520a through 520d, respectively. The outputs of each of 5 AND-gates 540a, 540f and 540k are connected to OR-gate 541a and the output of this OR-gate is applied to the input of 10 flip-flop 524a in the precounter. In like manner, each set of AND-gates interconnecting the space memory, indent memory and point size memory is connected to the respective flip-flops in the precounter 524 through one of OR-gates 541a through 541e, respectively.

Each set of AND-gates 540a through 540e, 540g through 540j, and 540l through 540o, is also supplied with an input from one of the flip-flops 545, 546, 547, respectively, shown 15 at the bottom of FIG. 21B. The flip-flop 454 is set for each horizontal step pulse received from the character generator during the production of a character while the flip-flops 546 and 547 are set on commands from the decoder circuit after an indent or a space command function has been presented by 20 the control record.

The third input to each of the AND-gates 540a through 540o is supplied from a pulse propagating circuit including a set of single shot multivibrators 550a through 550e. Thus, 25 when a command pulse is applied to the single shot 550a, it will in turn apply a pulse of a standard predetermined width to each of the inputs of AND-gates 540e, 540j and 540o. If the other inputs to any one of these are enabled, an output will be transferred through the OR-gate 541e to change the status of 30 flip-flop 524e in the precounter.

At the completion of the standard width pulse from single shot 550a, flip-flop 550b will trigger and apply a standard width pulse to the AND-gates connected to its output. In like manner, single shots 550c through 550e will trigger in 35 sequence to transfer the information stored in the space, indent or point size memories into the precounter 524. The particular information transferred depends on the status of the flip-flops 545, 546 or 547 which in turn depend upon commands from either the decoder or the character generator.

40 The output of the precounter 524 is applied along line 555 from the last stage flip-flop 524e to the storage counter 525 which includes seven flip-flops 525a through 525g.

Each of the precounting flip-flops 524 will change state 45 each time a positive going signal is applied thereto. Thus, the first signal applied to any one of the precounter flip-flops will cause it to go into the set state, and the next signal applied thereto will cause that flip-flop to reset. Upon the complete change of state of any one of the flip-flops in the precounter 524, an output signal will be applied to change the state of the flip-flop connected to its output. Thus, an enable signal from the forward-reverse flip-flop 556 will be applied on line 556a to the upper AND gates connected in the input circuits to the precounter flip-flops. Thus, when flip-flop 524a changes state, and then returns to its original condition, a pulse is applied to 55 the next flip-flop 524b through the now enabled AND-gate 557 causing flip-flop 524b to change state at that time. This arrangement forms a typical counting circuit which is apparent to those skilled in the art, and can be used to accumulate width 60 information of the character being generated.

The horizontal control circuit is also provided with an interpolation counter 526 including six flip-flops 526a through 526f, and a main counter 527 which includes seven flip-flops 527a through 527g. As seen in FIG. 20B, the interpolation counter 526 is connected to the storage counter 525 by gate means 560 with AND-gates 560a through 560f interconnecting storage counter flip-flops 525a through 525f and the interpolation counter flip-flops 526a through 526f. AND-gate 560g connects the remaining storage counter flip-flop 525g to the 65 main counter flip-flop 527a. The interpolation counter 526 is also connected to corresponding flip-flops 521e through 521j in the indent memory through AND-gates 560h through 560m, while the main counter 527 is connected to the indent memory flip-flops 521k through 521q by AND-gates 560n through 560t, respectively. The space memory flip-flops 520e

through 520g are also connected to the flip-flops comprising the interpolation counter and main counter through AND-gates 560aa through 560mm.

A pulse propagating circuit 561 applies a standard length pulse in succession to each of the AND-gates 560 when it is desired to transfer information from either the space memory 520, indent memory 521 or storage counter 525 into the interpolation counter 526 and the main counter 527. Space memory information will be transferred when the space memory flip-flop 547 is in the set condition, while the information in the indent memory will be transferred when the indent memory flip-flop 546 is in the set condition. The information contained in the storage counter 545, is transferred into the interpolation or main counters when an end of character signal on line 473 from the character generator is applied to set the end of character flip-flop 565. When this occurs, a signal on line 565a will enable each of the AND-gates 560a through 560g. Thus, by enabling one of the flip-flops 546, 547 or 565, and applying a pulse to the pulse propagating circuit 561, the information contained in the indent, space and storage flip-flops may be transferred into the interpolation and main counters.

Referring now to the operation of the horizontal control circuit and particularly to the storage of character size information in the precounter during the generation of a character on the face of the cathode-ray tube, the size of the character as represented by the information stored in the point size memory 523 will be multiplied by the number of horizontal step pulses received from the character generator. This multiplication occurs by transferring the information stored in the point size memory directly into the precounter for each horizontal step pulse. A horizontal step pulse, which is generated by the character generator and applied on line 412 each time the cathode ray tube beam moves horizontally one incremental unit is applied to set the horizontal step flip-flop 545. At this time, a positive level signal will be available on line 545a and applied to one input of each of AND-gates 540a through 540e. At the same time, a negative signal will be applied on line 545b to the one-shot multivibrator or single shot 567 which will in time apply a standard length pulse through OR-gate 568 to trigger the single shot 550a.

Each of the single-shot multivibrator in the horizontal control circuit are triggered by a negative going input signal and have an output pulse of a predetermined width. Once the single shot 550a is triggered, an enable signal will be applied to a second input of AND-gate 540e. If the point size memory flip-flop 523a contains point size information, its output will supply the remaining input to the AND-gate 540e and that information will be transferred at this time into the precounter flip-flop 524e. At the end of the standard width pulse from single shot 550a, a single shot 550b will trigger and enable AND-gate 540d to allow the information stored in the point size memory flip-flop 523d to be transferred into the precounter flip-flop 524d.

After each of gates 540a through 540e have received a pulse from one of the single shots 550a through 550e, single shot 550f will trigger and apply an output along line 569 to one input of AND-gate 570. The other input to this gate is assumed to have an enabling voltage applied thereto at this time, thus, the pulse on line 569 will pass through AND-gate 570 and OR-gate 571 to trigger the single shot multivibrator 573, the output of which will be applied on line 573a to reset the horizontal step flip-flop 545. At this time, flip-flops 546, 547 and 565 are also reset and the reset signal is also applied to flip-flop 575. With the flip-flop 545 reset, another horizontal step pulse may then be received to repeat the foregoing operation. Thus, for each horizontal step pulse received by the horizontal control circuit, the information stored in the point size memory will be transferred into the precounter 524 resulting in a multiplication of the point size factor by the number of horizontal step pulses.

In a preferred embodiment of the invention, the precounter circuit is designed to count a total of nine points and transfer a

single pulse to the storage counter 525. The precounter 524 senses point size from one-half point through eight points by means of the five storage flip-flops with the precounter flip-flop 524a sensing half point increments and flip-flop 524e sensing eight point increments. Since the precounter 524 can count to a total of 16 points, a means is provided to add a count of seven into the precounter after the precounter transfers a count to the storage counter and the transfer of point size information to the precounter is complete. This function is accomplished by the setting of the "add 7" flip-flops 575, as a result of the flip-flop 524e changing to the set condition. The output on line 575a is applied to one input of AND-gate 577 while the other input is applied on line 569 from the single shot 550f. Once an output is applied from AND-gate 577, the single shot multivibrator 578 is triggered to apply a single pulse to set a count of four into precounter flip-flop 524d. The trailing edge of the pulse from single shot 578 will trigger flip-flop 579 to apply a pulse representing a count of two into flip-flop 524c and trigger single shot 580 to apply a count of one into flip-flop 524b.

Since flip-flop 575 is set, the enable is removed from AND-gate 570 and the output from single shot 550f is not permitted to pass through AND-gate 570 to trigger single shot 573 and reset the system. However, the output of single shot 580 may be applied on line 580a to an input of OR-gate 571 thereby to trigger single shot 573 to reset the horizontal step flip-flop 545 and the "add 7" flip-flop 575. Thus, a count of seven will be added to the precounter 524 once the precounter has filled but after the point size information in the point size memory has completed its transfer into the precounter.

When the character generation is completed, an end of character signal is presented on line 473 to set the end of character flip-flop 565 and cause an enable voltage on line 565a to be applied to each of AND-gates 560a through 560g. Flip-flop 565 also has an output one line 565b which will enable OR-gate 585 and apply a signal along line 585a to trigger single shot 561a. The output of this single shot will enable one input of each of AND-gates 560i and 560mm, however, no information will be transferred since the other inputs will not all be enabled. The single shot 561a will trigger single shot 561b at the end of the pulse and the pulse will be propagated in like manner to each of the single shots 561a through 561m.

When single shot 561g is triggered, the information stored in the storage counter 525g will be transferred into the main counter flip-flop 527a. As the pulse propagates from single shot 561g through 561n, the information in the storage counter will be transferred into the interpolation counter. The output of single shot 561m is also placed through OR-gate 568 to trigger single shot 550a, although no information is transferred at this time, and eventually cause the system to reset. It is noted that the sequence of pulses from single shots 561 and 550 may transfer not only point size information but also space and indent information into the respective counter flip-flops.

The least significant digit flip-flop 528 has its input connected to AND-gate 586 which in turn has its input connected to the outputs of the precounter flip-flops 524d and 524e. It is only when both of these flip-flops in the precounter are in the set state that the least significant digit flip-flop will set. The output of the least significant digit flip-flop 528 and the outputs from each of the flip-flops in the interpolation counter 526 are connected to the interpolation D/A circuit and will control the horizontal position of the beam withing the $\frac{1}{8}$ -inch increment selected by the operation of the main counter circuit 527.

Referring now to the operation of the horizontal control circuit when an interword space is detected by the decoder, a space command signal will be applied on line 590 to set the space flip-flop 547. An output on line 547a will be applied to enable each of the AND-gates 540l through 540o interconnecting each of the space memory flip-flops 520a through 520d with the precounter flip-flops 524b through 524e, and to enable AND-gates 560aa through 560mm, interconnecting

the space memory flip-flops 520e through 520q with their respective flip-flops in the interpolation counter 526 and main counter 527. A signal is also applied on line 547b to the OR-gate 587 which in turn supplies an output on line 591 to the decoder to inhibit further operation of that element until the horizontal control circuit has completed its operation.

The output on line 547b is also applied to OR-gate 585, and the output from this gate triggers the pulse propagating network 561 thereby to transfer the information stored in the space memory to the main counter 527, interpolation counter 526 and the precounter 524. At the end of the information transfer sequency, the space memory flip-flop 547 is reset and the inhibit on line 591 is removed from the decoder to allow subsequent operation.

When an indent function is required, an indent signal on line 592 is applied to rest indent flip-flop 546. This flip-flop functions in a manner similar to that of the space flip-flop 547 and places an enable on each of the AND-gates 540g through 540j and 560h through 560t, places an inhibit on line 591 to prevent the further operation of the decoder until the information stored in the indent memory 521 is completely transferred, and triggers the pulse distribution circuits 561 and 550 thereby to accomplish the actual transfer of the space information stored in the indent memory into the main counter 527, interpolation 526 and precounter 524.

Each of the flip-flops comprising the precounter 524, the storage counter 525, the interpolation counter 526 and the main counter 527 may be reset by a signal from the decoder on line 318. This normally occurs when a new line of type is to be generated.

The horizontal control circuit 116 is also provided with means to reposition the beam after a single character or a line of characters has been generated to allow for the underlining of those characters, to permit the addition of accent and other like marks above any one of the characters or to reduce the intercharacter space which is automatically provided by the character generator to permit kerning. The reverse movement of the cathode-ray tube beam is accomplished by causing the interpolation counter 526 and the main counter 527 to count in a reverse direction. This is made possible in the circuit shown in FIGS. 21A through 21D by applying a command from the control record to set the forward reverse flip-flop 556 which in turn creates an enabling signal on output line 556b where it is then applied to the lower set of AND gates interconnecting the space and indent memories 520 and 521 with the precounter 524, the interpolation counter 526, and the main counter 527.

In an underlining operation, for example, the space memory 520 will be set in response to information on the control record to store the appropriate space information necessary to reposition the beam under the first character to be underline. The forward-reverse flip-flop 556 is then set upon a command from the control record and a space command signal, also from the control record, will set the space flip-flop 547 and supply the necessary signal to transfer space information from the space memory into both the interpolation counter 526 and the main counter 527. With these counters reset to the value predetermined by the control record, the proper major horizontal deflection circuit 600 will be selected and the interpolation D/A 660 will be adjusted and the cathode ray tube beam will be placed in the proper starting position for underlining.

OPERATION OF THE MAJOR HORIZONTAL DEFLECTION DIGITAL TO ANALOGUE CIRCUIT

In the preferred embodiment of this invention, the major horizontal deflection voltage applied to the horizontal deflection elements of the cathode ray tube is obtained from one of 64 separate major deflection horizontal D/A circuits 600, such as circuit 600a shown in FIG. 22, with the particular circuit in use determined by the status of the main counter 527. Since the voltage required to deflect and focus the cathode-ray tube

beam is not a linear function of the horizontal position of the beam, means are provided to insure that the characters written on the face of the tube are of constant size to minimize distortion and to insure that the spacing between characters is constant no matter where the characters are placed horizontally on the display face of the tube. For this purpose, the tube is divided into 64 $\frac{1}{6}$ -inch increments and each of the $\frac{1}{6}$ -inch increment is provided with separate control signals from one of the major deflection D/A circuits. Therefore, by selecting each major deflection horizontal D/A circuit in sequence, proper focusing and accurate and equal spacing of characters over the width of the entire face of the CRT may be obtained. Since the focus voltage required is symmetrical on either side of the center line of the tube, only half, or 32 of the major deflection horizontal D/A circuits need be provided with this focusing voltage information.

On a typical cathode-ray tube of the type used in this invention, a zero deflection voltage would be necessary to position the beam at the center of the tube while a minus voltage would be necessary to deflect the tube to the left and a positive deflection voltage necessary to move the beam of the tube to the right. Therefore, when writing a line of characters on the face of the tube, the beam would start at the extreme left-hand position which would require that the first major deflection horizontal D/A circuit supply the greatest negative voltage, and as the beam moves to the right, less and less negative voltage would be required until the beam passes the center line and then an increasing positive voltage will be required until the beam passes the center line and then an increasing positive voltage will be required from each of the succeeding horizontal D/A circuits selected.

Each of the major deflection horizontal D/A circuits, one of which is shown in FIG. 22, includes a NOR gate connected to the main counter 527 in the horizontal control circuit 116 (see FIGS. 10 and 21A-21D). The NOR gate in each major deflection horizontal D/A circuit has seven inputs, with each input attached to the seven flip-flops which comprise the main counter 527 in such a manner that only one horizontal D/A may be selected at a time. The particular outputs of the main counter flip-flops to which these inputs are connected will determine which one of the horizontal D/A circuits is selected by the operation of the main counter.

In this embodiment of the invention, a zero voltage signal applied to each of the inputs 601a through 601g is required to enable that particular major deflection horizontal D/A circuit and supply an output voltage to the horizontal deflection elements of the cathode ray tube. When this condition exists, both input transistors Q1 and Q5 will be in a nonconducting state. Transistors Q2 and Q6 will be in a conductive state, however, and cause both transistors Q3 and Q7 to also be in a state of conduction. With transistors Q3 conducting, the base of transistor Q4 will be at an effective ground potential and will cause transistor Q4 to also be in a state of full conduction, thereby providing a positive level voltage on line 605. The voltage on line 605 will be limited, however, to the voltage appearing on terminal 606 through line action of the clamping diode 607.

It is noted that when transistor Q4 ceases conduction, the voltage on line 605 will become negative with respect to the input voltage on terminal 606 and the clamping action will thereafter cease. In like manner, transistor Q8 is also in a state of conduction and the negative voltage appearing on line 610 will be clamped by the action of diode 611 to the voltage applied to line 612.

Since transistors Q1 and Q5 are in parallel, causing either of these transistors to conduct will reverse the function of each of the transistors in the circuits which follow. Therefore, since both the transistors Q1 and Q5 are connected in a typical NOR gate circuit, a negative signal applied to any of the terminals 601a through 601g will cause either of these transistors to go into a state of full conduction and remove both the positive and negative voltages from the output buss lines 605 and 610.

The buss line 605 supplied a positive controlled voltage through diode 615 and adjustment potentiometers 616 onto line 620. This voltage is designated as the horizontal size voltage and represents the voltage difference between the horizontal D/A circuit in use and the horizontal D/A circuit supplying the deflection voltage within the next succeeding $\frac{1}{2}$ -inch increment on the face of the tube and for horizontal and oblique D/A reference voltage through the point size control, later to be described. Potentiometer 616 may be adjusted manually to obtain the correct voltage for this line. The voltage supplied through diode 625 and adjustable resistor 626 on line 630 is designated as the vertical size voltage. A positive voltage is also supplied through diode 635 and potentiometer 636 onto line 640 and supplied the correct focus control voltage for the cathode ray tube.

The positive voltage from buss 605 is also available on terminal 645. By connecting a diode between this terminal and terminal 646, a positive voltage may be applied through the potentiometer 647 onto line 650 to provide a positive major deflection horizontal voltage for the cathode-ray tube. In the present example, however, diode 651 connects the line 650 to the negative buss line 610 so that a negative voltage is available on this line to deflect the beam in the cathode-ray tube to the left. It can be seen, therefore, that one design of a D/A circuit may be used to function both as the means to deflect the cathode-ray tube to the right and to the left of center.

OPERATION OF THE INTERPOLATION DIGITAL TO ANALOG (D/A) CIRCUIT

An interpolation digital to analogue (D/A) circuit is connected to the output of the interpolation counter 526 (FIGS. 10 and 12) in the horizontal control circuit and provides a voltage output proportional to the magnitude of the voltage applied thereto from the major deflection horizontal D/A circuit selected by the main counters and the status of the flip-flops in the interpolation counter. The output of the interpolation D/A circuit 660, the schematic diagram of which is shown in FIG. 23, is applied to the horizontal deflection elements on the cathode ray tube to make relatively minor changes in the horizontal position of the beams. The input to this circuit is obtained from the horizontal output on line 620 from each of the major deflection horizontal D/A circuits.

The function of the interpolation D/A circuit is to make minor variations in the voltage applied to the horizontal deflection elements of the cathode ray tube so that for every count in the interpolation counter 526 in the horizontal control circuit, the cathode-ray tube beam will move equal incremental steps horizontally across the face of the tube between the beam positions initially established by the output of the major deflection horizontal D/A circuits 600. In the present invention, only one interpolation D/A circuit 660 is provided and the voltage input to this circuit is obtained from line 620 which connects the interpolation outputs of all of the horizontal D/A circuits.

A circuit similar to that shown in FIG. 23 may also be employed as the minor deflection vertical, horizontal and oblique D/A circuit in the character generator, and the leading D/A circuit, since the maximum voltage output of this circuit is proportional to the voltage applied to the input terminal and may be made to vary in equal incremental steps as determined by the status of a set of flip-flops connected to the control terminals.

Referring now to the schematic drawing of FIG. 23, the interpolation voltage or the voltage representing the difference between the voltage output of the major deflecting horizontal D/A now selected by the main counters and the next succeeding horizontal D/A circuit on line 620 is applied to the interpolation D/A and to the base of transistor Q9 through a summing resistor R10. A reference voltage is also applied to the base electrode through summing resistors R11 and R12. The emitter electrode of transistor Q9 is connected directly to ground.

An external source of voltage is applied to terminal 665 directly to the collector elements of transistors Q11 and Q12 and through resistors R13 to the emitter electrode of transistor Q10. The collector electrode of this transistor is connected directly to the base of transistor Q11 and to the collector of transistor Q9. Therefore, the voltage at the collector element of transistor Q9 may be controlled by the current applied to the base of that semiconductor from the interpolation voltage on line 620, and a second reference voltage from line 666, and that current in turn will control the conduction of current through transistor Q11. Since the emitter of transistor Q11 draws current through resistor R14, that transistor in effect controls the voltage at the base of transistor Q12. The voltage on line 667, which is connected directly to the emitter of transistor Q12, is therefore proportional to but of opposite polarity from the voltage applied to its input on line 620 from the horizontal size output of the horizontal D/A circuits and the second reference voltage on line 666.

To provide stability and control over the voltage on line 667, a negative feedback path is provided by connecting the emitter of transistor Q12 to the base of transistor Q9 through resistor R15. The source of external power on terminal 665 is also applied through dropping resistors R16 and R17 and a Zener diode Z1. A line 668 is connected to Zener diode Z1 and the voltage thereon is held constant through the action of that diode and is applied as a bias voltage to the base electrode of each of transistors Q13 through Q19. The junction between resistors R16 and R17 provides the bias voltage for the base electrode of transistor Q10 which provides a type of regulator so that small variations in the external power supply voltage will cause the voltage at the base of transistor Q11 to be altered and compensate for the power supply variations thereby insuring that the voltage on 667 is proportional only to the input on line 620 from the horizontal size output of the major deflection horizontal D/A circuit and the second reference voltage on line 666. The emitter electrodes of transistors Q13 through Q19 are connected through appropriate resistors to the line 669.

In series with the collector circuits of each transistors Q13 through Q19 are switching transistors Q20 through Q26. The base of each transistor Q20 through Q26 is connected to the input circuit 670 consisting of seven inputs 670a through 670g, with inputs 670a through 670f connected to the six flip-flops which comprise the interpolation counting circuit 526 in the horizontal control circuit, while the input 670g is connected to the last significant digit flip-flop 528. Therefore, by controlling the voltage to the inputs 670 by the action of the interpolation counter and the least significant digit counter, selected various ones of transistors Q20 through Q26 may be switched off or into the nonconducting state.

Applying a zero level signal to any one of the inputs 670 will cause the corresponding transistor Q20 through Q26 to stop conducting and allow current to flow through the diode and resistor. Resistors R18 through R30 from a voltage ladder circuit, and then allowing current to flow through these resistors will alter the output voltage on line 675 which is ultimately applied to the horizontal deflection amplifier and then to the horizontal deflection coil of the cathode ray tube. Thus by causing one of the transistors Q20 through Q26 to stop conduction, additional voltage may be added to the voltage ladder due to the increase in current through the resistor and diode with that transistor.

The interpolation D/A circuit 527 thus described is a constant current voltage ladder which functions to receive the voltage applied on line 620, regulate and amplify that voltage, and pass it through a switching circuit which will give a variable voltage output on line 675, depending on the status of the counting flip-flop in the interpolation counter 526 and the status of the flip-flop 528 comprising the least significant digit circuit in the horizontal control circuit (FIGS. 10 and 21) and thereby partially control the position of the cathode-ray tube beam.

OPERATION OF THE REED RELAY CIRCUIT

The reed relay circuit shown in FIG. 25 functions to modify both the horizontal size voltage supplied on line 620 and the vertical size voltage supplied on line 630 from the selected major horizontal D/A circuit 600 in response to the point size of the character to be generated, as stored in the point size memory 523 (FIG. 21A) and supplies this modified voltage to the horizontal and vertical minor deflection D/A circuits 452 and 459 in the character generator (FIG. 17).

The reed relay circuit consists of nine separate relays each controlled by a transistor with the input of each transistor connected to a decoder circuit which senses the status of the flip-flops which comprise the point size memory 523. Since only point sizes between five points and nine points are sensed, a total of only four diodes connected to the various outputs of the flip-flops 523a through 523d in the point size memory (FIG. 21A) are required to select the proper reed relay circuit. As the point size of the character increases, the reed relay circuit will cause the voltage output for both the horizontal and vertical size of the character also to increase. Provisions are also made to alter the vertical deflection voltage in such a manner that the characters generated will appear on the same base line regardless of point size.

The single reed relay control circuit for supplying the proper voltage for a five point size character is shown in detail in FIG. 24 and includes four diodes forming a NOR gate with their inputs connected to the reset output of flip-flop 523a, the set input of 523b and reset input 523c and the set input of 523d. With this arrangement, all the diodes will have a common negative level voltage only when a five point character is to be generated. When this occurs, the voltage at the base of transistor Q3 will become negative and the transistor will conduct to energize the reed relay K1. With the contact of relay K1 closed, line 620 will be connected through resistor R35 to output line 620a and will supply the necessary horizontal size voltage to the minor deflection D/A circuit 459 in the character generator for the presentation of a five point character. Resistor R36 is connected to line 620 at this time and has a value such that a constant impedance load on line 620 will be maintained. Similarly, line 630 will be connected to line 630a through resistor R39 to provide the proper vertical size voltage with resistor R38 having a value sufficient to maintain a constant impedance load on line 630. Each of the remaining eight reed relay point size circuits functions in a similar manner with only the connections to the flip-flop comprising the point size memory being different.

In order to maintain the characters on a common base line regardless of point size, a resistor R39 (FIG. 10) is connected to line 630a and connected in parallel with the minor deflection vertical D/A in the character generator. Resistor R5 will add a small increment of voltage to the vertical deflection amplifier in proportion to the point size of the character and will cause the larger point size characters to be displaced vertically by an amount sufficient to cause the base of the larger characters to fall on the same base line as the smaller point size character.

OPERATION OF THE CATHODE-RAY TUBE INTENSITY CONTROL CIRCUIT

The circuit shown in FIG. 25 controls the intensity of the cathode-ray tube beam to compensate for the intensity of the characters being generated due to changes in point size. For characters of larger point size, the cathode ray tube beam will need to be brighter in order to produce an image which is relatively as bright as characters of smaller point size due to the larger spacing of the dots which form the image for the larger point size characters.

The intensity of the beam is controlled by the voltage applied to the control grid of the cathode-ray tube 115 from the adjustable tap on potentiometer R40 is in series with resistors R41, R42 and R43 in the collector circuit of transistor Q40.

This transistor is gated into conduction by the application of pulses on the base electrode on line 486 from the character generator 114 (FIG. 17). By shorting out either resistor R41 or resistors R41 and R42 together, or by leaving them both unshorted, it is possible to vary the intensity of the beam in three incremental steps.

Relay K10 has its contacts in parallel with resistor R41 while relay K11 has its contacts in parallel with both resistors R41 and R42. The windings of relays K10 and K11 are controlled by amplifiers 680 and 681, respectively. The input to amplifier 680 is connected to set output of flip-flop 523c, in the point size memory while the input to amplifier 681 is connected to the reset output of flip-flop 523d.

With this connection with the point size memory 523, both relays K10 and K11 will be deenergized for characters of either five or five and one-half point size. For characters having point sizes between six and seven and one-half, relay K10 will be energized, thereby shorting out only resistor R2 and increasing the current through potentiometer R1 and raising the voltage on the control grid of the cathode ray tube to increase the intensity of the beam. For characters having a point size between eight and nine, relay K11 will be energized thereby shorting out both resistors R2 and R3, further increasing the voltage on the control grid and the intensity of the beam.

OPERATION OF THE LEADING CONTROL CIRCUIT

A leading control is provided to vertically position the photographic film recording the images produced on the face of the cathode-ray tube and to make minor variations in the vertical positioning of the cathode-ray tube beam itself. The leading control is operated entirely by codes placed into the leading memory circuits from the magnetic control tape through the decoder and includes a control circuit for operating a stepping motor of the type which permits accurate and incremental movement of the film. The motor is geared to position the film vertically each time the presentation on the cathode ray tube changes and a new line of type or display is to be created. The leading control also impresses an electrical signal or a minor leading control signal on the vertical deflection elements to allow for small changes in the base line position of the displayed characters.

Referring now to FIG. 26, the twelve flip-flops comprising the leading memory 700 have their inputs connected to the data register 250 in the decoder (FIG. 12A) through cable 255. In this embodiment of the invention, only eight of the input lines from the data register 250 are utilized since the flip-flops in the leading memory 710 are divided into three sets of four flip-flops each. While corresponding flip-flops in each of the sets are connected to the same input lines, the information presented on these input lines will be transferred into the flip-flops of only one set when an additional signal, herein called the distribution signal, is applied to that set.

The distribution signals are generated by the decoder (FIG. 12B) when a set leading memory signal is developed in the decoder in response to a command from the control tape. The set leading memory signal will also appear on line 701 to enable each of gates 703, 704 and 705 to allow the distribution pulses from the decoder, which are thereafter applied sequentially on lines 337, 343 and 345, to pass through the gates and be applied on lines 707, 708 and 709, respectively, to cause the data appearing on the input lines to be stored in the three sets of flip-flops which comprise the leading memory. The method of recording information in the leading memory is therefore similar to the method used for storing information in the space memory circuit 520 in the horizontal control circuit (FIG. 21), previously explained.

Once the leading information is stored in the leading memory 700, a leading signal may be applied to initiate the operation of the leading motor and thereby move the film vertically with respect to the cathode-ray tube. To cause the film to move upwardly, a positive leading signal is applied from the decoder circuit on line 710 to set the forward reverse flip-flop

711. If desired, a pulse to cause negative leading could be supplied from the decoder on line 712 to place flip-flop 711 in its alternative state. Once the forward reverse flip-flop 711 is set, an enable will be applied on output line 712 and to AND-gate 715 in the forward-reverse counter and to one input of NOR-gate 717 in the stepping motor control circuit.

At the same time, a trigger pulse will be applied on line 722 into the clock mechanism 723 (shown in detail in FIG. 27), to start the clock sequence. The clock mechanism comprises a 10-kilocycle free-running multivibrator 725 operating the frequency dividing flip-flops or multivibrators 726, 727 and 728. The outputs of these flip-flops are connected to five NOR-gates 730 through 734 which in turn control the operation of the remainder of the leading control circuit. It is noted that the output of flip-flop 726 on line 735 is connected to each of NOR-gates 730 through 734. The first output 736 of flip-flop 727 is connected only to NOR-gates 731 and 734, while the second output on line 737 is connected to the remaining NOR-gates 732 and 733. The output of flip-flop 728 on line 738 is applied to NOR-gates 730, 731, and the remaining output on line 739 is connected to the remaining NOR-gates 732, 733 and 734.

Upon the receipt of a positive leading signal on line 710 (FIG. 26), a triggering pulse is applied on input 722 into clock 723 to set the flip-flop 724 (FIG. 27) which in turn applies an inhibit signal on line 743 into the control circuit 253 incorporated in the decoder shown in FIGS. 12A and 12B. Thus, while the leading operation is being conducted, the decoder is inhibited from further operation. The output of flip-flop 742 is applied on line 744 to NOR-gates 730, 731 and 734. At the same time, each of the three flip-flops 726 through 728 in the clock circuit are clamped in the reset state by an output on line 745. At this time, an output is applied on line 735 to NOR-gate 731. Gate 731 also receives an enable signal from line 736 and from line 738. A fourth input to this NOR-gate is available on line 746 from flip-flop 747 and on line 748 from flip-flop 742.

Upon a coincidence of signals at all five inputs of gate 731, an output pulse is applied through capacitor C1 and the diode along line 750 into a set of twelve flip-flops 751 which may be designated as the backwards counting flip-flops since their purpose is to provide a signal output when reaching a zero count. These flip-flops were previously placed into the reset state by a reset signal on line 752 when the system was initially turned on. Upon the receipt of the single pulse input on line 750, each flip-flop was placed in the unlevel state or set state as would be expected in a backward counting circuit.

As the multivibrator 725 continues to pulse the frequency dividing circuit, the first flip-flop 726 will go to the zero state and thus inhibit the operation of each of the NOR-gates. The second clock pulse from the multivibrator 725 will again return the first flip-flop to its one state and cause the second flip-flop 727 to change state. The third flip-flop at this point is unaffected. At this time there will be a coincidence of signals on NOR-gate 730 due to the enabling voltage now available on line 737.

The output of NOR-gate 730 (FIG. 27) is applied along line 754 to a set of gates 755 (FIG. 26), designated herein as the memory gates. These gates interconnect the output of the memory flip-flops 700 and the backward counting flip-flops 751. By opening these gates at this time, the information stored in the flip-flops in the leading memory 700 will be transferred into the backward counting flip-flops to reduce the count by the number of counts stored in the memory circuit.

The third pulse from the multivibrator 725 (FIG. 27) will again cause the first flip-flop 726 to disable each of the five NOR gates, while the fourth pulse from the multivibrator will set the first flip-flop 726 and cause the second flip-flop 727 to set again and clear the third flip-flop 728. Thus, with the third flip-flop cleared, an enable signal is applied on line 739 to each of NOR-gates 732, 733 and 734 while an enabling voltage is applied from the output of flip-flop 727 on line 736 only to NOR-gates 731 and 734. Under these conditions, NOR-

gate 734 is the only gate enabled and an output on line 746 will cause flip-flop 757 to set and in turn cause flip-flop 747 to set. With the flip-flop 747 now in a different state, the enabling voltage on line 746 to gates 730, 731 and 734 is now removed and at this time an enabling voltage is present on line 758 to thus enable future operation of that element.

The fifth clock pulse from the free running multivibrator 726 will again cause the first flip-flop to clear and inhibit the operation of gates 730 to 734, while the sixth pulse will set the flip-flop 726 and clear both the second and third flip-flops 727 and 728. Under these conditions, there will be a coincidence of signals on gate 732 since there is now an enable signal on line 760 from flip-flop 757. With gate 732 now enabled, a signal will be applied on line 750 into the backward counter to cause it to count backwards one more step at this time.

A pulse is also applied along line 761 (FIG. 27) and through inverter 762 (FIGS. 26 and 27) to the forward reverse counting circuit made up of flip-flops 763 and 764 and their associated gates. After every four counts on line 761, a pulse 20 from flip-flop 764 will be applied to either gate 717 or 718, one of which will supply an output to the forward-reverse gray code converter 767 depending on the status of the forward-reverse flip-flop 716. The converter 767 is a two-stage counter which supplies the signals to the amplifier circuits 768 25 which in turn drive the stepping motor 118 (FIGS. 8 and 10) in the proper direction causing the photographic material 119 to move.

At this time, only the NOR-gate 732 is enabled and pulses 30 from the clock circuit will be applied to the backward counter 751 and to the forward reverse counter to cause the motor to step and the backward counter to count simultaneously.

For each step of the stepping motor, the film is moved a distance equivalent to one point. Accordingly, by setting various information into the flip-flops in the memory 700, the film can be caused to move a specified incremental distance. In order to achieve finer control of the beam with respect to the film, a pair of output lines 770 and 771 are connected to flip-flops 763 and 764, respectively. These lines control a leading 40 D/A circuit 780 (FIG. 10) and cause one-quarter point changes in the vertical deflection voltage on the cathode ray tube between pulses to the stepping motor.

When the backward counter reaches a zero count, there will be a coincidence of signals on input line 775. This line is connected to an output of each of the counters in the backward counter circuit 751. With a signal on line 775, flip-flop 757 will change its state, thus placing an enable signal on line 766 to enable gate 733, while an inhibit signal will be placed on line 760 to prohibit further operation of gate 732 and the counting of the backward counter 751 and the operation of the stepping motor. Clock pulses passing through gate 733 will set flip-flop 777 and 778, and after four pulses, an output from flip-flop 778 will reset flip-flop 747. Returning an enable signal on line 746 will reset flip-flop 742 and thus return the entire system to its original state.

The phototypesetting system described hereinabove is therefore capable of presenting justified lines of type which may be recorded by a photographic medium such as photographic film or paper. Each line of type is generated by displaying one character at a time with the characters being selected from a character generating means, such as an optical character generating disc as described above, by a previously prepared control record. The character generating means of this invention automatically provides intercharacter spaces and therefore no additional commands from the control record are required during the generation of a single word. Interword spaces are precalculated to provide justified lines of type and the proper interword space information is stored for future use in the phototypesetting apparatus information. Thereafter a single command from the control record is sufficient to cause the proper interword space to be added between words as a line of type is created.

Since only a single command is required to generate a character and the intercharacter space and since a single com-

mand is all that is required to generate an interword space once the interword space information is stored in the phototypesetting apparatus, a minimum amount of time is required, therefore, to create a justified line of type on the face of the cathode-ray tube to be subsequently recorded by the photographic medium.

The phototypesetting apparatus as described above is also flexible in that the type may be quadded either to the right, to the left, or to the center, as well as tabulated or paragraphed upon a single command from the control record after the necessary positioning information is recorded in the control circuits to define the desired location for beginning a line of type.

The intercharacter spaces, as previously mentioned, are automatically provided by the character generating means, however, in certain operations, such as kerning, it is more desirable to have less intercharacter space than is provided normally. The control circuit of the phototypesetting apparatus herein described is capable of reducing the intercharacter space, again upon an appropriate command from the control record. This same circuit also allows for underlining of selected characters and permits the application of accent and other special marks above other selected characters.

Further flexibility in the operation of the phototypesetting apparatus herein described is permitted since several fonts of characters may be provided within the character generating means. Also, one font may be mechanically substituted for any of the fonts within the character generating means to provide for further variety in the types of characters which may be generated. With several fonts in the character generating means, electrical selection of one of the fonts may be made to the electrical output from an existing font by electronic means to cause the characters to slant and thus give them an italic like appearance when they are displayed on the cathode-ray tube. Also the size of the type recorded on the photographic means may be controlled electronically in response to commands from the control record without requiring a change of font in the character generating means.

Thus, the phototypesetting apparatus herein described provides the same flexibility in its operation as other, more conventional, phototypesetting systems, and, in addition, is faster in its operation.

While the methods and forms of apparatus herein described constitute preferred embodiments of the invention, it is to be understood that the invention is not limited to these precise methods and forms of apparatus, and that changes may be made therein without departing from the scope of the invention which is defined in the appended claims.

Having thus described our invention, we claim:

1. An apparatus wherein characters are to be formed along a line on a surface by a beam by supplying a plurality of first and second deflection signals in sequence for deflecting the beam with reference to first and second coordinate axes to generate a succession of visual images which define the configuration, said apparatus comprising means for providing a position signal to position the configuration at a selected location along a said line extending across a said surface and configuration generating circuit means comprising means for receiving command signals for providing first and second deflection signals having magnitudes dependent upon said

60

selected location for sequentially deflecting the beam to generate a sequence of image elements which are spaced apart at least in a direction parallel to one of said axes and which define said character, means for varying the magnitudes of 5 said deflection signals in dependence upon said selected locations, said configuration generating circuit means including spacing control means for a coordinate axis for selectively changing by a selectable factor the magnitude of the deflection signals for the coordinate axis to vary the said spacing 10 between said images, and means for blanking said beam between said spaced images.

2. An apparatus as set forth in claim 1, wherein said command signal receiving means includes means for multiplying a reference signal by a factor determined by said command signals to provide one of said first and second deflection signals.

3. An apparatus as set forth in claim 2, including beam control means for varying the intensity of said beam.

4. An apparatus as set forth in claim 3, wherein said beam control means is controlled by said spacing control means.

5. Apparatus for displaying configurations on a surface with an energy beam and comprising:

means for deflecting a said beam with reference to first and second perpendicularly related axes;

first control means for applying positioning signals to said deflecting means to position said beam on said surface at a selected position in accordance with first command signals;

second control means for applying configuration signals to said deflecting means to sequentially position said beam relative to at least one of said axes to provide a plurality of incrementally spaced images spaced parallel to said one axis and which define a said configuration, said second control means including means for varying the magnitude of said configuration signals in dependence upon the said selected position;

configuration size control means for, in response to size command signals, changing the magnitude of said configuration signals to thereby change the said spacing between said images along said one axis and thereby change the size of said configurations; and,

means for blanking said beam between said spaced images.

6. Apparatus as set forth in claim 5, including configuration memory means for storing digital representations of various configuration sizes and in response to a said size command signal providing digital signals representative of a particular configuration size.

7. Apparatus as set forth in claim 6, including a plurality of configuration signal modifying means for respectively modifying the magnitudes of said configuration signals in dependence on said digital representations.

8. Apparatus as set forth in claim 7, including digital decoding means for decoding said digital signals to activate a selected one of said configuration signal modifying means to correspondingly modify the magnitude of said configuration signals.

9. Apparatus as set forth in claim 5, including means for varying the intensity of said energy beam in accordance with the configuration size in effect.
